APPARATUS FOR FOLDING FLEXIBLE SHEETS
Rudolph Funk, Furlong, Pa. (Valley Road, Jamison, Pa.)
Filed Nov. 21, 1958, Ser. No. 775,427
60 Claims. (Cl. 270—63)

This invention relates to apparatus for folding flexible sheets of precise or random lengths and widths into a standard-sized folded packet and pertains particularly to the automatic folding of blueprints and the like.

The uses of great numbers of blueprints in industrial organizations is well known. The filing and storage thereof, without losing ready location and withdrawal of same, has become a problem of increasing complexity. It has been customary to manually fold same into an approximation of a predetermined folded packet size for such filing and storage. This manual procedure is quite disadvantageous and expensive, because; of the labor costs of such folding; of folding inaccuracies inherent in the procedure, rendering given packets incompatible in dimensions with other packets of a related series; in many cases the folds effect turned-in corners which affect the ability of the opened blueprint to lie in a general plane when opened out for inspection as well as unduly increasing the thickness of the packet; in many cases the folding procedure may present the outer fold surface bearing the title block, as of smaller dimensions than the packet, so that the title block, in the filing and storage condition, is below the level of others of adjacent packets, and may therefore be hard to locate; and finally, in many cases the important title block is not located on the outside area of the outside fold and cannot be located either for filing or locating without opening up the packet.

It will be understood in this description that although the invention is primarily directed toward the folding of blueprints, whether such prints are made of paper or of any other flexible fabric, it is applicable to the folding of any sheets, whether blueprints or not. Usually such sheets have a readable top surface, and a blank lower surface. It will also be understood that the sheets are those which are initially substantially or generally planar, and may be, generally speaking, of various thicknesses, provided each still possesses the attribute of flexibility, by which is meant the ability to be folded upon itself and to generally retain the folds until unfolded.

It is among the objects of the invention to provide a sheet folding apparatus, which; is safe, both to the operator and to the sheets being folded; is rapid; is of highly compact size; is of relatively low cost; is of uniformity of edge dimensions of the folded packet substantially regardless of the number of folds and the thickness of the packet; can receive and fold sheets of random length into a predetermined packet area; can effect exact predetermined folded packets of sheets of random lengths and widths automatically without any adjustments; can fold sheets of different widths into the same predetermined packet size; is operated and controlled by a single operator, who merely preliminarily positions a sheet and effects the complete folding cycle by a single, momentary, motion of a treadle or the like, or by an electrical or mechanical impulse from an automatic sheet feeding device, when the latter is provided; primarily folds the sheet length-wise on transverse lines in successive alternate directions of folds, hereinafter designated as accordion folds, and secondarily effects either none, one or more cross-folds, according to the width of the instant accordion folded sheet; always produces the first accordion fold on a predetermined transverse line at a predetermined

2

distance from the advancing edge of the sheet, regardless of the length or width of the sheet; incorporates constantly driven creasing, folding and feeding drums, each mounting creasing and folding mechanism, complementary of each other in the respective drums, with means insuring an exact cyclic relation of the drums before the advancing sheet contacts said drums to insure that the first fold on the first transverse line is always of the same distance from the advancing sheet front edge; is so organized in its cyclic progression that with any instant sheet preliminarily positioned in a standard unforgettable manner by the operator, the title block of the given or instant print always appears at the same place on an external surface of the packet; and many other objects and advantages 10 will become more apparent as the description proceeds.

In the accompanying drawings, forming part of this description:

FIG. 1 represents a plan of an illustrative sheet A, such as a blue print to be folded according to the invention, 20 of purely illustrative dimensional proportions, showing the location of the title block thereon, and indicating in dotted lines the crease lines of the accordion folds to be effected on the sheet.

FIG. 1a represents an edge view of the sheet of FIG. 1, 25 with the direction of the accordion folds indicated by small creases leading into the respective crease line apices.

FIG. 2 represents a plan of the sheet in rudimentary packet form with an illustrative three panels of accordion folded creasing in respective overlying and underlying 30 relation, showing in dotted transverse lines the lines of cross folds to be effected.

FIG. 3 represents a perspective view of the rudimentary packet organization shown in FIG. 2.

FIG. 4 represents a perspective view of the rudimentary 35 packet after receiving a first cross-fold, forming a semi-packet.

FIG. 5 represents a perspective view of the complete packet, after the semi-packet of FIG. 4 has received its second cross fold, and is ready for delivery.

FIG. 6 represents a partially fragmentary perspective 40 view of the apparatus and the enclosing housing taken toward the front thereof.

FIG. 7 represents a related perspective view of the device as shown in FIG. 6, but taken from the rear thereof.

FIG. 8 represents a fragmentary, partially diagrammatic, section through the apparatus, showing the crease drums with their axes lying in an inclined plane, and showing an illustrative form of tilted tray for receiving the accordion folded rudimentary packet.

FIG. 9 represents a related section through a modified organization of crease drums and tray, in which the axes of the drums are in a horizontal plane, and the rudimentary packet is delivered to a generally horizontal tray.

FIG. 10 represents a fragmentary vertical section 55 through the forward, accordion folding section or part of the apparatus, showing the stationary cam organizations cooperating with the rotatable components mounted on the drums for respectively operating the crease rolls and extensible blades in the drums.

FIG. 10a represents a diametric section through one of the crease drums taken on line 10a—10a of FIG. 11.

FIG. 10b represents a fragmentary elevation of a modified form of feed rolls for imparting a preliminary crease in a sheet before it reaches the accordion crease drums.

FIG. 11 represents a fragmentary plan, partially in section, of the cams and cooperating elements at one end of the respective crease drums.

FIG. 12 represents a fragmentary side elevation of the

elements comprising the compound lever mounted on the frame adjacent to one of the brackets supporting the upper primary feed roll actuatable by transitory deflection of a treadle, showing in full lines the lever in its bracket supporting position, and showing in dotted lines the secondary position of the lever in which the bracket is free to drop relative to the lever pursuant to downward treadle or related motion.

FIG. 13 represents a fragmentary section, partially in elevation, showing the treadle connection to the compound lever for releasing the feed roll supporting bracket, and the cam and detent organization for permitting the upper primary feed roll to fall with its mounting bracket.

FIG. 14 represents a fragmentary plan, partially in section, showing the blade lock-out (or hold-in) mechanism in its ineffective inoperative position, in full lines, and showing its effective operative position in dotted lines.

FIG. 14a represents a fragmentary detail of FIG. 14, showing the detent holding the lock-out lever in its inoperative relation.

FIG. 14b represents a fragmentary detail showing the side groove cam for forcing the lockout lever out of the operative into its inoperative attitude.

FIG. 15 represents a fragmentary side elevation of the mechanism including the side groove cam shown in FIG. 14 with frame components removed for clarity.

FIG. 15a represents a fragmentary elevation, partially in section, of a modified form of lock-out mechanism, in a simplified, presently preferred form, showing in full lines its operative lock-out position, and in dotted lines its inoperative position. In the instant case, this is disclosed, for ease of disclosure, in a plural drum organization having their respective axes in a common horizontal plane.

FIG. 16 represents a fragmentary plan of a portion of a modified form of tray, with complementary downwardly turning crease and feed rolls, for helping to effect a cross fold, and staggered fingers for alternatively tilting the effective bottom of the tray, for guiding the accordion folded panels into proper relation relative to the tray.

FIG. 16a represents a schematic fragmentary section of the floor of the modified tray of FIG. 16 showing its relation to the downward crease feed rolls, shown in FIG. 16.

FIG. 17 represents a fragmentary detail of the mounting of the downward crease-feed rolls of FIGS. 16 and 16a.

FIG. 18 represents a fragmentary end elevation of the tray and roll organization of FIG. 16, partially in section.

FIG. 19 represents a section, partially in rear elevation, of one form of mechanism for effecting cross folding of an accordion folded sheet, in rudimentary packet form, as disposed on a tray according to the disclosure of FIG. 16.

FIG. 19a represents a presently preferred mechanism in elevation, partially in section, for effecting cross folds in an accordion folded rudimentary packet.

FIG. 20 to 26a inclusive, represent purely schematic diagrams of the structure and functions of the parts correlated with the tray of FIG. 16, shown in one choice of attitude of the respective drums, i.e., as suggested in FIG. 9.

FIGS. 27 to 33 inclusive represent purely schematic diagrams of the structural and functional interrelations of the drums and their various cams for effecting the cyclic folding procedures of the invention, shown in another choice of attitude of the respective drums; i.e. in reverse of the disclosure of FIG. 8.

FIG. 34 represents a fragmentary elevation of a tilting cam unit for accelerating the withdrawal of the projected blade of one drum from the crease rolls of the complementary drum.

FIG. 35 represents a fragmentary vertical section taken on line 35—35 of FIG. 34.

Before discussing the particular illustrative mechanism

involved it will be helpful to explain what is to be accomplished thereby, in the conversion of a generally planar sheet, such as a blueprint, into a packet of predetermined bi-lateral dimensions. For purely illustrative example, it will be assumed that the ultimate dimensions of such ultimate packet are to be 8½ inches by 11 inches. Obviously, if desired, it could be of any other dimensions, such again, for purely illustrative instance, it might be 9 inches by 12 inches, or any other arbitrary dimensions. The illustrative 8½ inches by 11 inches is presently preferred, as it comports well with certain standard sizes of blueprints.

For illustrative purposes, therefore, as noted, it will be assumed that the sheet A, of FIGS. 1 to 5, is the sheet to be folded, and, for expository purposes is of major width, as later explained, that it is of rectangular form and has a front or leading edge B, 34 inches wide (an even multiple of 8½ inches) a side edge C, 33 inches long, and the title block D is at the corner of the reading side of the sheet at the intersection of front edge B and side edge C. It will be understood that these dimensions of sheet A are illustrative only, and various changes may occur therein causing either the width along edge B to be greater or less than an even multiple of the illustrative 8½ inches, or the length may be greater than an even multiple of the illustrative 11 inches. Reference is made hereinafter to the manner in which the apparatus takes care of odd dimensions of sheets.

At any rate, for illustrative purposes, the sheet A as described, with an illustrative length of 33 inches, is just such as to receive two evenly spaced accordion folds, along lines indicated at 1 and 2 in dotted lines in FIG. 1, parallel to the front edge B. The edge B and the line 1 define a front panel A4, line 2 defines the rear end of a median panel A5 and the front edge of a rear panel A6, and each panel is substantially 11 inches by 34 inches. According to the invention the formation of the first accordion fold on line 1, to establish panel A4 and an edge of panel A5, is always made in such direction of fold, as suggested by the small crease leading into line 1 in FIG. 1a, that the front panel A4 is bent downwardly under panel A5. This folding places the title block D on the surface of panel A4 as presenting downwardly and outwardly. The next accordion fold on line 2, completing the definition of central panel A5 and the leading edge of rear panel A6, is always in the opposite direction from that of the first fold, as indicated by the small crease leading into line 2 in FIG. 1a, so that panel A5 presents upwardly above the first panel A4, whereas panel A6, overlying the middle panel A5, presents downwardly, and has the usually blank rear surface of the sheet exposed upwardly.

With completion of the two accordion folds, or as many more as may be required by the length of the sheet in excess of the illustrative 33 inches, a composite accordion folded rudimentary or intermediate partial packet, of at least the three panels described is produced, as shown in FIGS. 2 and 3. As will be noted in those figures and from what has been described the title block is on the lower surface at the corner, presenting downwardly. The composite rudimentary or intermediate assembly, according to the illustrative case, is substantially 11 inches by 34 inches.

Assuming a sheet width of the 34 inches mentioned, the composite rudimentary panel 7 of FIG. 2 is folded with a crossfold, along a median line 3, to form a semi packet, composite panel assembly 6, of one cross fold and of six layers, and having lateral dimensions of 11 inches by 17 inches. At this juncture the title block D is on the outer exposed half of the panel A4 in the upper left hand corner thereof. Finally, a second crossfold, on line 4, is made, producing the final packet 9 of the desired dimensions of substantially 8½ inches by 11 inches and of twelve thicknesses of sheet. The final cross-fold on line 4 continues the presentation of the title block D on the upper left

hand corner of the outer surface of the packet 9. The packet is then ready for delivery, filing and storage.

Referring to FIGS. 6 to 9, and as shown in one or another of these figures, a compact vertical enclosing housing support 10 is provided, having suitable access doors (not shown), and at the forward upper portion has a sheet entrance opening 11 and at the lower rear portion has the packet delivery chute 8.

The support 10 is preferably provided toward its upper end with an external horizontal shelf or table 5, aligned with the lower edge of the sheet entrance opening 11. The shelf or table 5 and opening 11, each wider than the sheet width capacity of the machine, extend substantially the width of the housing 10. The table 5 mounts a lateral guide 15 on its right side edge (looking along the table toward the front of the housing 10), and illustratively the side or lateral guide 15 is comprised of vertical pegs as shown. A constantly driven primary lower feed roll 13 is journaled in the housing inwardly of the opening 11, the surface of which is substantially tangential to the upper surface of the table 5, and the feed roll 13 is adjacent to the inwardly disposed vertically adjustable leading-edge stop pins 16 (FIG. 6). The latter pins in their upward disposition are of such small vertical extent as to just intersect the sheet A along its front edge B, when the sheet is disposed on table 5 with its side edge C engaging the side guide pegs 15 and slid forward on the table to abut stop pins 16, and this stopped attitude of the sheet A is effected by the operator in positioning the sheet. In the thus stopped position of the sheet, the forward portion, behind edge B, overlies the lower primary feed roll 13, in harmless general contact therewith as the roll rotates. At this juncture also the title block D, is located in the forward right hand corner of the sheet, adjacent to the front edge B abutting adjustable stops 16, inside of the opening 11. The feed roll 13, as shown in FIGS. 8 and 9, is clockwise driven, and by itself has no feeding function on the sheet A.

In order to effect positive primary feed of the sheet A, a rotatable primary upper feed roll 12 is provided, journaled in vertical slots 12' in the forward ends of a pair of spaced brackets 20-20 (FIG. 13), pivotally mounted in the housing, with the feed roller 12 normally vertically spaced above the driven roller 13. By compound timing means to be described, the upper feed roll 12 drops or moves downwardly with the forward ends of the brackets, 20-20, to engagement with the upper surface of the positioned sheet A, in synchronism with the downward withdrawal of the stops 16 (as illustrated in FIG. 13). The sheet A is thus compressed against the driven roll 13 and the rotations of the latter effect primary feeding of the sheet across the table 5, across the line of stops 16, and into a pair of secondary feed rolls 21-22. The preferred gravitational pressure of feed roll 12 against the sheet A is to protect the sheet and also to prevent injury to the operator should he inadvertently get his hand between the roller 12 and sheet A.

It is a feature of the invention that the contact of the upper primary feed roll 12 with the sheet A is purely transitory, being maintained just long enough to insure inward feed of the sheet until the advancing edge B passes between secondary feed rolls 21 and 22. By mechanism to be described, substantially as soon as the sheet A has been gripped between the secondary feed rolls 21-22 to continue the inward feed, the brackets 20-20 are actuated to raise the upper primary feed roll 12. Although in synchronism with this motion, the vertically adjustable stops 16 may also be raised, this stop disposition has no adverse effect on the feed, as the sheet A simply slides over the upper edge or edges thereof as a general continuation of the sliding of the sheet as it is fed inwardly of the apparatus.

In order to effect smoothness of the secondary feed, it is preferred that although the rolls 21 and 22 may be geared together to rotate oppositely, in the preferred case,

the lower secondary feed roll 22 is journaled in the frame on a fixed axis and turns clockwise, the upper secondary feed roller 21 is journaled to float vertically a small distance relative to lower feed roller 22, while rotating counterclockwise, to account for variations in thickness of the sheets A. If desired, the secondary feed rolls 21 and 22 need not be geared together, and the upper roll 21 may simply rest gravitationally on driven roll 22, or on the sheet A passing between the rolls.

10 The secondary feed rolls 21-22 advance the leading edge B of the sheet A toward the meeting line of two oppositely rotating synchronously driven complemental creasing drums 23 and 24, which are geared together and preferably constantly driven during the operation of the apparatus. As shown, in all figures except FIGS. 27 to 33, the lower drum 24 is driven clockwise and the upper drum 23 is driven counterclockwise, so that a sheet A entering between same is fed inwardly thereby, while also receiving the appropriate accordion folds, previously described. In said FIGS. 27 to 33, this operation is reversed, but only for illustration. It will be understood that the actual folding necessitates high speed, accurate, supplemental mechanism, and requires various internal creasing and expelling mechanisms, and internal and external cams 25 and the like for various cyclically successive functions during the cyclic progression of the creasing drums 23 and 24.

It will be understood that a definite predetermined linear distance exists between the meeting line of the upper and lower primary feed rolls, across the meeting line of the secondary feed rolls 21-22 and to the common intersection of drums 23-24. It will also be understood that, as explained, the initiation of the feed by the primary feed rolls is closely coordinated with the predetermined relative angular relation of the drums so that an advancing tab of the sheet is passed between the drums just before the blade of the upper or one drum becomes radially juxtaposed to the crease rolls of the other or lower drum. With a different distance between the center line of the primary feed rolls and the meeting line of the drums 23-24, and with a predetermined angular relation of the drums at the instant of primary feed initiation, as by the dropping of the upper primary feed roll 12, it will be understood that the secondary feed rolls 21-22 may be omitted. It is preferred to use the latter, however, as they establish control of the sheet despite the subsequent separation of the primary feed rolls, while locating the drums 23 and 24 well within the enclosure housing 10, to facilitate proper delivery of the accordion folded sheet 50 on the tray.

The creasing drums 23-24, as illustrated in FIGS. 10 and 10a, are complemental to each other in structure and creasing functions. Each comprises a hollow metal drum, having axially extending generally radial 55 openings on centers peripherally 180° apart. The drums may each have a superficial external coating of rubber or like friction material, as illustrated at 23' of FIG. 10a, so as to grip and advance a sheet, or may grip by virtue of a serrated pattern on the periphery of the metal drums. One of the longitudinally extending openings is a slot 31, for the radial extension and retraction of a blade 32. The other opening 28, is wider and contains a pair of complemental rubber or like-coated or serrated metal crease rolls 43 and 44, both substantially tangential to the projected circumferential periphery of the drum. The center of the opening is the meeting line of the crease rolls, and this is diametrically opposite the centerline of the blade 32. It is a feature of the invention that the crease drums 23-24 are continuously 65 driven in opposite directions so as to continuously feed an advancing sheet, while subjecting the sheet to the successive accordion folds. In the cyclic progression of the two crease drums 23-24, the blade 32 of one first drum becomes juxtaposed to the crease rolls of the complemental second drum, and after 180° of angular travel 70

the blade of the second drum becomes juxtaposed to the crease rolls of the first drum. Means, to be described, are provided for cyclically projecting and retracting each blade as it approaches juxtaposition to the crease rolls of the other drum, and for synchronously rotating the juxtaposed crease rolls of the other drum in one direction to draw in and crease an area of sheet projected ahead of the advancing blade and then rotating the same crease rolls in the opposite direction during the continued rotation of the crease drums to expel said fold.

The peripheral areas of the respective drums are calculatedly such with relation to the centers of blade 32 in slot 31 and of the crease rolls 43 and 44 in opening 28, that exactly the illustrative 11 inches of sheet ultimately exists between the front edge B thereof and the first fold 1, and between folds 1 and 2, 2 and 3, etc. The paper slippages incident to the formation of each crease fold are calculable. Due to this calculable slippage the leading or front edge B of the sheet A must be somewhat beyond the common center line of the drums 23 and 24 at the instant the blade of one drum is exactly opposite the crease rolls of the other drum. As the first juxtaposition of a blade and crease rolls at the center line of the drums is immediately behind the front edge B of the sheet, a premature fold would be effected at the edge B if measures were not taken to prevent it. As will later be described two different organizations of blade lock-out are provided for preventing the formation of such premature and undesired fold.

A discussion of the slippages involved may be helpful. There are two distinct slippages that occur as each panel A4, A5, A6 etc., feeds into crease position. As the blade begins to form the paper into the V between the contiguous crease rolls, the panel already past this point slips backward a distance equal to the difference between the two crease roll arcs that the paper contacts just prior to the actual gripping of the paper by the crease rolls and the straight line distance between the center of the crease rolls ($=2 \times$ crease roll radius). This slip, again, is in a direction opposite the direction of paper feed, thus representing a calculable shortening of the instant panel. From the instant the grip of the crease rolls is effected there is a contrary slip of the following panel caused by the fact that the feed rolls, traveling with the instant drum, have a motion relative to the main drum and this relative motion causes the paper to accelerate its motion ahead of the instant drum and prior feed rolls, slipping forward with respect thereto as the paper is drawn between the crease rolls to form the crease.

These two slips are of critical importance when:

- (1) Computing the main drum diameters.
- (2) Computing the distance from the common center line of the main drums to the stop pins 16.

It will be understood that it is because of these slippages that the leading edge B of the paper must be ahead of the common center line of the drums when the blade and crease rolls are just opposite each other to furnish the exact illustrative 11 inches between the leading edge B and the first fold 1, and that it is this condition that necessitates holding out of the blade.

As previously explained, creasing and folding the sheet by drums 23-24 requires the sheet to be deflected out of its generally planar course between the drums, by the blade of one drum moving radially of its drum across the advancing sheet to preliminarily crease the sheet about the blade and to force this creased area between the crease rolls of the opposite drum outwardly of their common circumferential meeting line, where the completion and ejection of the fold is consummated. It is important, in this creasing operation, that the blade not insert the sheet to the common centerline of the complementary crease rolls, as this would substantially re-

quire the advancing edge of the blade to at least approach if not traverse said common center line and this would form a fold about a radius at the edge of the blade which is less than sharp or acute and require more time. It is also important, in this connection, that the blade at its extreme outer projection not only not traverse the common center line, preferably, but also that it be out of direct abutting engagement with the respective crease rolls, as shown in FIG. 13, although within the circumferential line of the drum between the outer arcs of the crease rolls. The projected blade thrusts against the sheet toward the crease rolls in a preliminary crease or fold which is taut against and wrapped partially around arcs of the respective crease rolls, as shown in FIG. 10. With the sheet under tension against these arcs, rotation of the crease rolls inwardly, by their frictional contact with areas of the preliminary fold, draw in the latter between and across the common meeting line of the crease rolls, creasing it at its apex and compressing it together adjacent to the apex. Reversal of the direction of rotation of the crease rolls, positively ejects the creased fold, while imparting a secondary creasing to the apex thereof as the latter passes outwardly across the common meeting line of the crease rolls. It will be seen that with such organization, there can be no sharp accordion folding unless the blade and crease rolls are operative as just described.

The means for effecting the initiation of the inward feed of sheet A, after its stopped preliminary setting against the relatively short vertical pegs or stops 16, is one which incorporates a time delay, used when necessary until in the cyclic progression of the parts everything is properly set for inward feeding progress of the instant sheet. While this initiation of the feed of the sheet into and through the apparatus may comprise any electrical switch means actuating desired circuitry in the apparatus, it is preferred that the control comprise a mechanical device. These may operate functionally with automatic sheet feed, if desired. In a purely illustrative form thereof the operator's initiating mechanism comprises a movable treadle or like lever 14. To simplify the operator's functions it is further preferred that the mechanical system operated by the treadle be by a mere tripping function, by which the treadle can be actuated and immediately released, in place of mechanism that must be manually held until the completion of the time delay period, the completion of all folds, or the like. According to the invention, actuation and immediate release of the treadle initiates the complete cyclic functioning of the apparatus to the ultimate delivery of the accurately shaped folded packet.

The schematic FIGURES 8 and 9 illustrate the general organization and functioning of the apparatus from the initial drawing-in and accordion folding of the sheet to delivery outwardly thereof to a receiving tray 25, etc. for the reception of the accordion folded partial or rudimentary packet 7, which tray is so organized and mounted as to facilitate cross-folding, as shown in FIG. 19. In FIGS. 8 and 9 the tray is shown as having a lower tray-surface 25 and left and right side (front and rear) walls 27 and 26. In FIG. 8 the tray is shown tilted relative to the horizontal so that as the front edge B of the first panel A4, resulting from the first accordion fold 1, drops into the tray, the leading edge B and thus this panel is deflected downwardly to prevent crumpling, or other misalignment with the tray surface 25. As will be later explained additional means are preferably provided for effecting this important result. FIG. 9 is to illustrate that the creasing drums need not be in inclined relation as in FIG. 8, but can be provided with both axes in a common horizontal plane. In FIG. 9 the bracket-controlling cam 70 (FIG. 13) is separate from and above drum 23, but is driven in synchronism therewith. The delivery in FIG. 8 may be to a horizontal tray as well. It will be understood that 75 with the tray in the disposition shown in FIG. 9, the mov-

able components of the later described figures will be preferably incorporated so as to effect proper and positive guidance to the accordion folds of the sheets. In any case, the trays of FIGS. 8 and 9 are susceptible to the cross folding accomplished as in FIG. 19.

The foregoing exemplifies the conversion of a substantially planar sheet into a rudimentary accordion folded packet on the tray, with the panels in substantial parallelism with each other and with the tray, and having a length longer in the line of the folds than in width transverse of such folds.

Reference is made to FIGS. 10, 10a and 11, for a disclosure of parts at least of the creasing drums 23 and 24, and their associated creasing elements, to assist in understanding of FIGS. 8 and 9, and other figures. FIGS. 10 and 11 illustrate the cams and like cooperating elements.

Drums 23 and 24 are mounted by end plates 45' for rotation with respective drive shafts 30 and 30, journaled in the end walls of the housing 10. Each drum (FIG. 10a), has a blade slot 31 extending longitudinally axially, of the instant drum, through which the creasing blade 32 can be cyclically projected and retracted. This function is attained in retraction by means of axially projecting blade extensions 32', mounting cam rollers 50, engaging the inner surface of fixed internal cams 51, outward of each drum at the opposite extremities thereof. For extension suitable spring biasing means 32a are provided between each blade 32 and its instant shaft 30, for urging the blade 32 outwardly through its slot 31, when the position of the roller 50 with relation to the internal recess 52 of the fixed cam permits. After the roller 50 moves into the internal cam recess 52, and the blade 32 is projected resiliently radially outward, it will be seen that, cyclically, with rotation of the instant drum, the rollers 50 move out of the recess 52 and retract the blade 32.

In this connection it will be appreciated that the blade 32 is to move outwardly in entering the cam recess 52 and to move radially inwardly as the roller 50 rides out of the cam recess 52, during the rotation of the drums. This, by space limitations and by design criteria requires a very rapid thrusting in and out motion of blade 32 limiting the outward tip of blade 31 to a path along which it will not contact and possibly damage the rubber sheath on crease rolls 43-44. High cam pressure angles on the pull-out side of recess 52 of internal cam 51 cause noisy operation and high mechanical loads. To the end of an easy and positive means for retracting the blade in facilitation of rapid pull-out of blade 31 without the imposition of untoward forces on the drums and cams, the mechanism shown in FIGS. 34 and 35 may be preferred. Referring to these figures, the fixed cams 51 at each end of the drums may comprise a unitary body 51' juxtaposed to the end of both drums 23 and 24, having a lower recess 350, and juxtaposed to a frame extension 10' having a boss 351 extending through a suitable aperture in the cam plate 51'. The frame extension 10' is suitably apertured to receive a spring biased indexing stud or plunger 352, extending transversely across the recess 350, normal to the plane of the cam plate 51'. A generally flat guiding lever element or operator 353 is provided, pivotally mounted on an axle 354, threaded into the boss 351. The element or operator 353 on its rear face has two suitably spaced indexing recesses 355 and 355'. The element 353 is preferably partially asymmetrical in contour with relation to a median longitudinal axis and comprises a front edge 356 from which a pair of sloping guiding or camming surfaces diverge downwardly, as at 357 and 358, each leading by a rounded edge into a semi-cylindrical recess, respectively 360 and 361. Recess 360 is only partially arcuate and has a lower edge surface 362 which is generally linear and tangential to the arcuate portion of the recess 360. Preferably the recess 361 is more arcuate and approaches a semi-circle. The remainder of the edges of the element may be anything desired as they play no part in the operation of the tilting lever or operator.

According to the position of the lever element or operator the respective recesses 360 and 361 register laterally, in whole or in part with the given cam recesses 52. Although obviously this guiding tilting element 353 may be formed of any material, it is preferred that it be formed of a suitable synthetic resin, and preferably of "Nylon" or other resilient material.

With the parts as shown in FIG. 34 the element 353 is tilted to the left, counterclockwise, about the pivot 354, and is resiliently held therein by entrance of the indexing plug 352 into the juxtaposed recess 355. The drum 23 has rotated to the degree that the roller 50 of the blade 32, under the bias of the springs 32a, simultaneously enters the cam recess 52 and the element recess 360. At this juncture the blade has been projected radially outward toward the juxtaposed crease rolls of the drum 24. The surface edge 362 is angularly divergent from the inner cam surface 51. Continued rotation of the drum 23 forces the roller 50 against the generally linear edge 362, exerting a moment on the element 353 with reference to its axle 354, urging the element to turn clockwise on its pivot. This motion is accompanied by the turning of edge 362 toward tangency with the inner surface of the cam 51', forcing the roller 50 inward until it and the surface 362 attain such relative disposition that the roller 50 is deposited on and continues to ride on the inner periphery of the cam. At this juncture the element has tilted to its maximum degree and the indexing stud has been forced out of one recess 355 and the element has moved to dispose the stud in the other indexing recess 355'. Synchronously the tilting of the element has brought the recess 361 into lateral substantial registration with the cam recess 52 of the drum 24. When, in the cyclic progression of the drums, the roller 50 of the blade 35 of drum 24 enters into the cam recess 52 of the cam 51', it also enters the recess 361 of the element 353. Continued motion of the roller 50 with the drum 24 forces the element counterclockwise to force the roller outwardly to disposition on the inner surface of the cam 51' of the drum 24. If by mischance of any sort, the element 353 is improperly cocked for the approaching roller 50, the sloping edge surface 358 or 360 (depending upon which roller 50 is then approaching the element), is engaged by the roller and the roller rides and pushes upon the then juxtaposed surface 358 or 360, to tilt the element into position for the proper reception and subsequent retraction of the instant roller 50.

Referring to FIGS. 10 and 11, each drum mounts internally a crease roll 44 on a shaft 45, journaled in the end walls 45'. Shaft 45 mounts a pinion gear 46. Each drum axially externally mounts a sector gear 33, on the end of an arm 33', pivoted to the adjacent end wall 45' at 34. The sector gear 33 is in constant mesh with a pinion gear 35 keyed to a shaft 36 journaled in the outer free ends of oscillatable arms 37-37, pivotally mounted on the instant shaft 30 of the given drum. The shaft 36 mounts a crease roll 43, internally of the instant drum, and complementary to crease roll 44. Spring means 42, bearing against arms 37, yieldably urge the crease roll 43 toward crease roll 44. The sector gear arm 33' between the pivot 34 and the sector gear 33, mounts an actuating roller 39, moving within a fixed internal cam 40. A suitable spring 41 urges the sector gear arm 33' and roller 39, against the inner periphery of the internal cam 40. Internal cam 40 has a camming internal projection 38, sloping in both directions angularly from its crest. Shaft 36 of crease roll 43 mounts a pinion gear 47 in constant mesh with pinion gear 46, so that a folded sheet entering between the complementary crease rolls 44 and 43, and yieldably moving them relatively apart, does not disrupt the meshing of the pinion gears which cause them to rotate oppositely.

It will be seen that during most of the travel of an instant drum, the sector gear 33 is at one limit of its travel and the crease rolls are stationary in the rotating drum. It will also be understood that as the crease rolls are general-

ly tangential to the periphery of each instant drum (as shown in FIG. 10a), the space for reception of the blade guided fold is generally symmetrical of a radial line tangential to both crease rolls. It will also be seen that once in each cyclic rotation of each drum, the roller 39 rides inward on one slope of the cam projection 38 causing the sector gear to rotate the crease rolls in such relative rotations as to pull in and crease an area of sheet pushed into it by the blade of the complementary drum, followed by outward riding of the roller on the opposite surface of the cam projection 38, causing such relative rotation of the crease rolls as to eject the same sheet area. It will be noted that this function of outward extension of the blade of one drum to push the area of sheet into the crease rolls of the complementary drum and to withdraw, in synchronism with the intake of the area into creasing contact with the complementary crease rolls, followed in synchronism by the ejection of the creased area, is functional with the continued rotation of the complementary creasing drums. As the respective drums 23 and 24 continue to turn and to feed the advancing sheet, the latter is given alternately opposite accordion folds for location of the composite accordion folded sheets on the receiving tray bottom 25, directionally determined according to which drum presents the creasing blade to the moving sheet, as will be clear. It will be understood that this cyclic progression of turning of the creasing rolls in the respective drums to take in and complete the folds of one portion of the sheet and then to eject same by the reversing of the roll operation is continued for the full length of the blueprint or sheet A. Just as the running of the creasing rolls in one direction and then in reverse, is functional with the rotation of the respective drums, due to the operation of the fixed cam 40, so also is the projection and retraction of the blade 32 relatedly controlled in exact synchronism with the crease rolls by fixed cam 51.

A basic function of the present invention in securing its highly accurate and efficient results lies in the feature of automatically feeding the sheets into the machine in such timed relation, and in such length, as to force the formation of the first accordion fold, on line 1, in a correct place every time while control of the sheet is maintained through all stages of the folding manipulation. To the end of insuring complete feeding control, while the advancing sheet advances just exactly the right predetermined distance to receive the first accordion fold, the operation of the treadle and its associated mechanism will be described.

Reference is made to FIGS. 12 and 13. Having placed the sheet A against the stops 16 forwardly and laterally against the lateral guide edge 15, and with the title block D in its proper position as indicated in FIG. 6, the operator steps on the treadle 14, pushing it all the way down as far as it will go, and then releases same. The purpose of the treadle organization and the associated parts, to be described, is to insure that the feeding and creasing mechanisms are in exactly the right place cyclically before the paper is advanced beyond the initial setting against stop 16. It will be understood that if an automatic sheet feeding device is provided, operative, for instance, when the trailing edge of a sheet passes a given point in the apparatus, this can provide a means for effecting an automatic simulation of a manually operated device like the treadle disclosed. Upon the depression of the treadle or its automatic actuation, a number of things occur which will now be described.

The first consideration is the time delay by which the complementary drums attain exactly that relative rotative position whereby the advancing edge B of a sheet A, in its forward and inward feed by the primary and secondary feed rolls travels just that distance and in that time to permit the advancing edge B of such sheet to be engaged between drums 23 and 24 to establish and maintain control of the sheet while rotating thereafter just the distance that will force the formation of the first accordion

fold on line 1, at the predetermined distance from edge B. In the illustrative case, the said 11 inches. Therefore the time delay initiated by the actuation of the treadle 14, is primarily concerned with the properly timed dropping of brackets 20—20 to that datum attitude of upper primary feed roll 12, at which it engages the sheet against the rotating lower primary feed roll 13, in synchronism with downward withdrawal of the stop 16 out of the path of the sheet, to start the inward feed of the sheet in exact correlation with the exactly proper rotative attitudes of the drums 23 and 24, as has been previously described.

Still referring to FIGS. 12 and 13, the treadle 14, pivoted to the frame at 14', is biased upwardly by a suitable spring 52, and is pivotally connected, at both ends of the apparatus, to a link 53, moved vertically downwardly upon treadle deflection. As noted, if desired this may be an automatically controlled device in place of the manual operator disclosed. The upper end of each link 53 is pivotally connected to a compound lever organization, formed of a dogleg lever 54, pivoted to the frame at its upper end, at 55, on an axis generally parallel to the longitudinal extent of bracket 20. Each dogleg lever 54 is pivoted to swing transversely relative to the contiguous bracket 20, and on its forward edge is formed with a detent shoulder 56, for engagement under bracket 20, in the elevated condition of the latter. The dogleg lever 54 has a lower foot extension 57, upon which transversely U-shaped main lever 58 is pivoted, as at 60. The inner end of the foot 57 has a recessed lower surface 61, against which a transverse stop pin 62, mounted on the main lever 58, may abut. The dogleg lever 54 mounts a transverse pin 63 adjacent to and just below the detent shoulder 56. An arm 64 is pivoted to the frame 10 and extends beside the dogleg lever 54, and on its upper edge has a recess 65. The arm 64 is biased upwardly toward the pin 63 by a suitable spring 66. When detent shoulder 56 is under bracket 20, the pin 63 of the dogleg lever is engaged upwardly by the upwardly biased arm 64, out of registration with upper recess 65 therein.

When the operator depresses the treadle, which depression may be momentary only, or the apparatus otherwise effects a related function, the links 53 pull the compound levers, comprised of the dogleg and main levers, 45 downwardly and rearwardly about the pivots 55, into the position indicated in dotted lines in FIG. 12. At this juncture pins 63, with dogleg levers 54, have been pivoted to a position over recesses 65 in arms 64 and the latter under spring bias, have snapped upwardly, and pins 63 have entered recesses 65 in arms 64, holding dogleg levers 54 in their attained, secondary, retracted, position. The detent shoulders 56 have been moved out from under the instant brackets 20. At this juncture, if no other limits were placed upon them, both brackets 20, and feed roll 12, would fall by gravity and initiate feeding of the instant sheet A. Pursuant to release of the pressure on the treadle 14, upward movement thereof permits the links 53 to move upwardly, but this motion is operative only on the main levers 58, which swing on their pivots 60 on the feet 57, and assume a new position in which transverse stop pins 62 are out of contact with recessed surfaces 61. However, in relation to the situation noted, there are two additional factors which must be correlated and rendered operative, before the brackets 20 can drop 65 to place feed roll 12 into datum feeding juxtaposition to roll 13 to progress the sheet inwardly into the apparatus.

Referring to FIG. 13, and some other figures, it will be seen that the upper creasing drum 23 mounts externally, at both ends of the apparatus, a driven cam 70, having 70 both an internal and an external cam surface, of importance in this present connection. As shown in this figure (and some of the schematic diagrams, to be discussed), the rotatable cam 70 has an internal cam surface 71, comprising an internal periphery 73 of large radius, and an internal periphery 72 of smaller radius. The peripheral

surfaces 72 and 73 merge into each other by sloping internal surfaces, of which one is a cam fall surface 74 and the other is a cam rise surface 74'. The cam 70, rotatable with the crease drum 23, also has an external cam surface of large radius 77, merging, by sloping cam rise surface 79, and cam fall surface 79', into a cam surface of smaller radius 76.

Each bracket 20, is pivoted to the frame, as at 20', and, as noted, journals, vertically loosely, the axle ends of the primary upper feed roller 12, at their front ends, on one side of the pivots 20', and, on the other sides of the pivots, toward their rear ends, mount laterally projecting cam rollers 75, riding against the internal cam surfaces 71.

Trip release arms 80, pivoted to the frame at 80' respectively mount rollers 78, which are urged toward the external cam surfaces 77, by suitable springs 91, and, toward their free outer upper ends, have downwardly projecting detent shoulders 81, disposed for overlying and latching down the rear ends 90, of the brackets 20.

It will be understood that so long as bracket rollers 75 run on internal cam surfaces 72 of the cams 70, in rotation of the latter, the brackets 20 will be held, with relation to their pivots 20', with the primary upper feed roller 12 elevated. It will also be clear that when the feed roller 12 has fallen, for its transitory initiation of inward feed of the sheet, this can only occur when the rollers 75 are juxtaposed to the internal cam surfaces 73 of larger radius. Furthermore, with the brackets so swung on their pivots that the feed roller 12 is disposed upon the sheet A for feeding same, when rollers 75 engage the appropriate internal sloping cam rise surfaces 74, the brackets are forcibly swung on their pivots to elevate the feed roller 12. Relatedly it will be noted that with the detent latch shoulders 81 on arms 80 overlying the ends 90 of the brackets 20, with the latter elevating the feed roller 12, with the rollers 78 riding on external cam surfaces 76, the latches 81 will prevent falling of the brackets and feed roller 12, until the rollers 78 of the detent arms ride outwardly on the appropriate sloping cam rise surfaces 79. This latter action forces the arms 80 rearwardly, and release the rear or inner ends 90 of the brackets 20 for upward movement to lower feed roll 12 when permitted by the cyclic progression of the drums.

It will be seen therefore that there are three separate devices utilized to control the precisely timed drop of primary feed roll 12. Of primary importance is the inner contour 71 of cam 70, whereof cam fall surface 74 permits, through roller cam follower roller 75, and bracket 20 to which roller 75 is affixed, primary front feed roll 12 to be dropped into contact with the sheet A, at just the precise instant with respect to the cycle of drums 23 and 24, that will cause the sheet to feed just that right distance into drums 23 and 24 necessary to intercept and be engaged by the blade and crease rolls to form accordion fold 1 at its correct location. The delay arrangement of FIG. 12 and FIG. 13 has been incorporated to permit the operator to ready the machine to feed on the subsequent approach of cam fall surface 74, by initial actuation of the link 53, as by depressing the treadle 14. This arrangement also restricts feeding action so that it does not immediately succeed a depression of the treadle. Safety latch arm 80 prevents premature fall of the bracket 20 pursuant to depression of the treadle, despite the unlatching removal of latching shoulder 56 from under the bracket 20 by swinging of the compound lever 54-58 about the pivot 55, during that interval in which cam follower roller 75 is adjacent to but still spaced from the inner cam surface 73. Latch arm 80 is cammed away from its position as a detent to the inner end 90 of the bracket 20 by sloping rise cam surface 79 engaging cam roller 78 at the very instant that cam follower roller 75 moves downwardly (radially outwardly), on cam fall slope surface 74, to permit gravitational lowering of the bracket 20 and the primary feed roll 12.

The leading edge or sheet advance stops 16, are mounted on transverse bar 85, connected to and extending between the respective brackets 20-20, between primary feed roll 12 and pivot 20', and the stops are of such vertical extent as to drop below the line of the positioned sheet A, with the dropping of the upper feed roll 12 to its datum feeding position.

As an incident to the drop of upper primary feed roll 12, the bracket 20, in dropping, impinges against the outer free end of each pivoted arm 64, forcing the latter counterclockwise and lowering the recess 65 therein to release the pin 63, permitting the dogleg lever 54 to move clockwise under the bias of spring 67, until the outer edge of the detent shoulder 56 pushes laterally against the side of the bracket 20, in position to engage thereunder, with a snap action, when the forward end of the bracket 20 is elevated by rise cam slope surface 74'. When the bracket 20 has dropped about the pivot 20', after withdrawal of the detent 81, in due course the cam surface 77 progresses far enough to permit roller 78 to move on cam fall slope 79', and release the outward pressure on the arm 80, through said roller 78, pursuant to which the detent end 81 of the arm is biased against the rear end 90 of the bracket 20. When the brackets 20 and roller 12 are forced upwardly, about bracket pivots 20', by downward pressure on roller 75 from slope 74', the detent shoulder 81 again passes over and latches the rear end 90 of the bracket, locking bracket 20 safe against inadvertent or premature response to treadle depression and dogleg lever retraction, as might occur during that portion of the rotation of cam 70 when cam follower roller 75 is out of contact with cam surface 73. The detent thus holds the upper primary feed roller upwardly preventing premature sheet feed and precluding any sheet feed until the proper initiation of the succeeding feed cycle.

Recognizing that the sheet must advance far enough through the feeding mechanisms to be engaged by the meeting feeding surfaces of the complementary drums 23 and 24, and that due to the geometry of the feeding section of the apparatus and the two sheet slippages previously alluded to, a tab of the sheet adjacent leading edge B must extend slightly beyond the common main drum center line when leading edge B passes between complementary blade and crease rolls on that instant center line, it becomes important to prevent a premature fold by the adjacent juxtaposed blade and crease rolls.

It is necessary, according to the invention, to provide a blade hold-out, or, radially, a "hold-in," for that blade 50 in drum 23 which normally would effect a premature crease closely adjacent to the leading edge B of the sheet A. Reference is made to FIGS. 11, 14, 14a, 14b and 15, for a disclosure of one form of blade hold-out.

Shaft 30 of the lower drum 24, at each end mounts a 55 cam 95 having a side cam groove 96, and the latter contains a lateral (axial) knockout cam element 97. A compound blade hold-out lever is provided at each end of drum 24, comprising at one end a blade hold-out arm 100, and at the other end a latching arm 110, with the 60 compound lever pivotally connected medially on a cocked axis 99 to an arm 101, pivoted on a horizontal axis 101'. The blade hold-out arm 100 has an upper edge surface 102, which is suitably concaved for its function, to be described.

65 The arm 100 of the compound lever mounts a laterally extending roller 103. A spring device 104 surrounding the pivotal axis 99, biases the compound lever clockwise (in the plan of FIG. 14), urging the roller 103 toward the cam 95. Until the compound lever is released to 70 respond to the urge of the spring 104, the roller is juxtaposed to and rests upon the hub 95' of the cam 95. In this attitude or configuration the arm 100 is sufficiently offset laterally (axially of cam 95), and vertically downwardly, as to avoid impingement by the blade extension 75 32' in its rotation with the upper drum 23.

To maintain this normal attitude of the compound lever, a bracket 111 is mounted on the bracket 20, mounting a vertically extensible spring biased stop 112, normally projected vertically behind the lever end 110, to prevent its response to the urge of the spring 104.

When, by the mechanism described, the instant bracket 20 and the upper feed roll 12, drops, to place the feed roll 12 in its datum position to start the inward feed of the sheet, the bracket 111 also drops relative to the compound lever arm 110, thus withdrawing the vertical stop 112 from behind the edge of arm 110, permitting the compound lever arm to swing on axis 99 relative to arm 101, by the force of spring 104, and moving the blade hold-out arm 100 toward the cam 95, as indicated in dotted lines in FIG. 14, to an attitude in which, as the extending roller 103 is juxtaposed to and enters cam groove 96 at its smallest radius, the arm 100 moves into vertical alignment with the advancing blade extension 32' of the blade 32 of the drum 23. At this juncture the arm is below and out of intersecting relation with said extension 32'. The extending roller 103 is received in and encompassed by the cam groove 96, and as the lower drum 24 and the cam 95 rotate, counter to the rotation of the upper drum 23 with its blade 32, the compound blade hold-out lever 100—101 rises arcuately upwardly (about axis 101'), due to the contour of the cam groove 96, moving arm 100 vertically until its upper concave surface 102 is positioned for intersection by the advancing extension 32' of the blade of drum 23, to forcibly hold said blade 32 radially inward to preclude any premature action thereof relative to the advancing sheet, and thus precluding any premature creasing and folding of the leading edge B of sheet A. Radial restraint (hold-out) to both ends of blade 32 through its extensions 32' is provided through similar mechanisms at each end of drum 24. During this continuous feeding sequence, the mechanism already described elevates the brackets 20 and upper primary feed roll 12, bringing up the yieldable stops 112 under the arms 110, in the then cocked attitude of the latter as indicated in dotted lines in FIG. 14. However, the stop is resiliently biased so that the mounting brackets 111 can elevate with the brackets 20 to their normal positions, depressing stop 112 under extension arms 110. However, as will be clear, the rollers 103, as an incident of the cocking of the compound levers by the springs 104, having entered laterally into the side cam grooves 96, ride in these grooves until in due course they are laterally ejected therefrom by riding up on knockout cam elements 97. This ejection forces the compound levers to turn on their axes 99 against the force of the springs 104, until the arms 110 move out of registration with the yieldable stops 112 into the full line position shown in FIG. 14, at which the spring biased stops 112 raise and are engaged by the side edge of instant arms 110, to hold the lockout levers out of action for the remainder of the instant accordion folding cycle. Synchronously the levers 100—101 have lowered gravitationally until rollers 103 again ride on hubs 95'.

As a preferred alternative to the blade lock-in system just described, reference may be made to FIG. 15a. In this figure parts that are common to the earlier description bear the same characters. This organization simplifies the mechanical structure involved. Referring to this figure a bell crank cam lever 308 is provided, pivoted at 309, detented counterclockwise against the clockwise bias of spring 310, and having a concave face edge 311 on one arm to correspond to the minor radius of blade cam 51 when caused to be pivoted into the hold-out position indicated in full lines in FIG. 15a. The lever 308 is normally positioned and detented in the position indicated in dotted lines, under the bias of spring 310, in which attitude the concave face edge 311 is retracted out of intersection with the roller 50 of the blade 32 of the upper drum 23. The bell crank 308 has a substantially horizontal arm 312, above which is located a vertical exten-

sion 313 mounted on bracket 20. When bracket 20 falls about its pivot 20', as previously discussed, the extension 313 abuts the horizontal arm 312, and forces the lever 308 counterclockwise about the pivot 309, moving the concavely contoured edge radially toward the axis 30 of the drum 23, into position to be intersected by the roller 50 on the blade 32 of this drum, forcing the blade inwardly, or at least preventing its radial outward projection. A detent link 315 is pivoted to the frame at 319, is biased clockwise by a spring 320, mounts a cam roller 316, and has a terminal detent shoulder 314, disposed to engage over and to latch down the horizontal lever arm 312, to hold the latter in the full line position until roller 50 has traversed across and beyond the rise and fall contours of the recess 52 in the internal cam 51. At this point the roller 316 on link 315 is struck by projection 317 on drum 24 (or some other camming element) and pushed to the left (counterclockwise), retracting shoulder 314 from the horizontal arm 312, permitting the bell crank lever to respond to the bias of spring 310 and to move clockwise, retracting the concave edge 311 from intersection by the roller 50 of blade 32 of drum 23, and permitting the lever to attain the position of rest indicated in dotted lines. It will be seen that the modified blade hold in operates once on the dropping of bracket 20 and throughout the remainder of the accordion folding cycle it is inoperative.

It will be understood that it is only a small area or tab of the advancing sheet adjacent to its leading edge B that is engaged between the drums 23 and 24, peripherally beyond the blade of the upper drum 23, during the brief functions interval of the described blade hold-out mechanism. While superficially, as has been explained, it might be assumed that this area would lengthen the width of the first panel A4, beyond the stated predetermined width, this is not so. This is for the important reason as stated, that when a fold is made as a result of creasing and folding the sheet by the complementary blade and crease rolls of the drums, material is drawn into the fold from both sides, and the small extended area just mentioned is just that which is absorbed in forming the first fold. The apparatus is calculated and designed to effect this important result. Before proceeding with the description of the next or cross fold devices it might be well to emphasize that all mechanisms involved in blade control, front feed roll control and hold-out are preferably duplicated at both ends of the apparatus, while, preferably crease roll function is single ended.

It will be understood that with the mechanism as so far discussed the properly located sheet progresses through the feeding and creasing procedures, effecting alternate accordion folds, of the same width for the full length of the sheet. Illustratively then, a rudimentary or subpacket is provided as shown in FIGS. 2 and 3, dropped eventually into a tray or support, preliminary to cross folding. It has been pointed out that it is desirable that the advancing edge B of the first panel A4 engage the tray surface at an acute angle so as to guide it and all subsequent panels into proper disposition on the tray or support. It will be clear that if the advancing edge B of panel A4 strikes a surface to which it is generally normal, as in FIG. 9, for instance, there is the possibility that the sheet may crumple or otherwise jam up. On the other hand, if a tray is disposed as in FIG. 8 to avoid this initial crumpling, because of the relatively acute angle between the advancing first panel and the tray bottom, there is nothing of similar effectiveness for guiding the second panel into its proper relation. Therefore the tray dispositions of FIGS. 8 and 9 are illustrative, and under favorable conditions are quite usable. However, it is preferred to provide a modification of the disclosures of these figures, to attain the maximum accuracy of flat centered plural accordion folds, as disclosed in FIGS. 16 to 19a inclusive, on a generally horizontal tray or support plate facilitating cross folding.

Referring to these figures, and to FIGS. 20 to 26 in-

clusive for diagrammatic disclosures, there are provided in the housing 10, vertical supports 130 (of which but one is shown in FIG. 16), mounting a horizontal support plate 129, having at least one transverse opening 139, within which is mounted, in general tangency to the tray bottom or support plate 129 a pair of oppositely rotatable downward feed rollers 150 and 151 (driven by means to be described). Above the bottom plate surface 129, primary shafts 133 and 134 extending the full length of the tray, are suitably journaled on the vertical supports 130, in parallel transversely spaced relation to each other, and these shafts are respectively controlled in oscillation by arms 135 and 136 respectively, by means disclosed in the schematic figures mentioned. These shafts respectively mount series of radially projecting pins, 138 on shaft 133, and 140 on shaft 134. Tubular shafts 141 and 142 are provided for rotation on and relative to the respective shafts 133 and 134, and are respectively controlled in oscillation by arms 144 and 145. The tubular shafts mount series of alternately mutually staggered fingers, respectively fingers 147 on tubular shaft 141, and fingers 148 on tubular shaft 142. These fingers occupy desired areas above the bottom tray or horizontal support plate surface 129, short of the feeding rolls 150 and 151, or of such additional numbers of the latter as will be described.

Feed rolls 150 and 151, parallel to the respective staggered fingers 147 and 148, are mounted on transverse shafts 152 and 153 respectively, and the latter are geared together by pinion gears 160 and 162. These are suitably continuously driven as by a belt 159, and are yieldably urged toward each other by journaling one shaft, such as 152 in the support and journaling the other shaft 153 in a pair of arms 162, pivoted to the support at 163, and with a spring bias 164 operative on the arms to urge the feed rolls yieldably together. This is shown in FIG. 17. As will be explained in connection with other figures, and as shown in dotted lines in FIG. 16a, a transverse or cross folding blade 161 can be juxtaposed to the accordion folded panelled sheet to force a cross fold into the panels and into the space between the rolls 150 and 151.

The transverse relatively staggered fingers 147 and 148 have tray-defining upstanding flanges at each end, respectively 147' and 148', as continuations of the respective fingers themselves. These effect discontinuous sides to the tray, similar to sides 26 and 27 of tray 25 of FIGS. 8 and 9. It will be noted that the tubular shafts 141 and 142 are peripherally slotted to receive pins 138 and 140 respectively, extending radially of internal shafts 133 and 134, the radial planes lying between certain of the staggered fingers to permit oscillation of either the shafts 133 and 134 or of the tubular shafts 141 or 142 independently.

The feed of the accordion folded sheet as it is progressively delivered from the drums 23 and 24, in conjunction with the operation of the respective sets of fingers of the tray is quite important, because of coincidental functions of the apparatus. The collateral mechanism and functions of the feed, are shown schematically in FIGS. 20 to 26 inclusive.

FIG. 20 indicates the starting position of the last described mechanism, in which the fingers 147 and 148 on the respective tubular shafts are down, and lie in a substantial plane above the bottom horizontal support plate surface 129, and the pins 138 and 140 on the inner shafts are vertical. This latter condition maintains until after the accordion folded sheet has been delivered to the tray formed by the fingers 147 and 148.

FIG. 21 adds to the disclosure of FIG. 20, in that it discloses a pair of external cams 180 and 181 (shown in FIG. 11), driven by the respective shafts 30 of the drums 23 and 24, and normally out of camming contact with rollers 196 and 197, to be described. In this figure the advancing edge B of the sheet, prior to the formation

of the first accordion fold, has moved downwardly to a position in which it intercepts a beam from a light projector or lamp 170 incident on a phototube and relay organization 171. Responsive to this relay actuation, 5 a suitable solenoid and spring organization 199 is actuated in the proper sense to force camming rollers 196 and 197 into camming relation with the outer peripheries of the respective cams 181 and 180, to cyclically depress and raise said rollers. This is schematically indicated in FIG. 21a. In FIG. 21 and related figures, 10 the cams 180 and 181 control the oscillations of the respective tubular shafts to raise and lower one set of staggered fingers, in alternation to the elevation and lowering of the complementary staggered fingers. Thus 15 a suitably guided rod 190 is provided having at its outer and a cam-engaging roller 197 (laterally controlled by the solenoid), and at the other end being pivoted to the free end of arm 144, at 193 to control the tilting of fingers 147. Relatedly the shaft 30 of drum 24 mounts 20 a cam 181, for controlling the oscillations of tubular shaft 142 by means of a suitably guided rod 195, mounting a cam-engaging roller 196 at one end, and pivotally mounted at its other end to the free end of arm 145, as at 191, for relatedly controlling the raising and lowering 25 of the series of fingers 148.

It will be seen that from the initially horizontal attitude of the staggered fingers 147 and 148 of the tray in FIG. 21, in the rotation of the cams to the position indicated in FIG. 22, the left hand tubular shaft 142 has been so rotated that the fingers 148 are elevated so as to guide the advancing edge B downhill, so to speak, to cause the panel A4 to repose on same in general parallelism therewith leading edge B juxtaposed to the then vertical tray-defining upstanding flange 147', while the fingers 147 remain substantially horizontal. The oncoming panel A4 is deposited on the raised tray element 148 until fold 1 is adjacent to the elevated tray corner at which juncture tray 148 is lowered in synchronism with fold 1 of the descending sheet, until, in due course, the fingers 148 are 30 dropped into the horizontal, just as, cyclically and synchronously the roller 197 is depressed by its cam to swing the shaft 141 to elevate its fingers 147, upwardly, as indicated in FIG. 23. Thus in alternation the fingers on one side raise and lower while synchronously in alternation the fingers on the other side raise and lower. 35 Thus each successive panel and fold of the oncoming accordion folded sheet is received by the instantaneously juxtaposed raised tray member and guided or lowered therewith toward the horizontal into ultimately compact registered relation on the tray bottom. The successive folds are successively tilted in one direction and then the other. This alternate raising and lowering of the tray bottom maintains until the final accordion fold has been accomplished, and the final panel (illustratively 40 A6), has been moved toward the tray. At this juncture, as shown in FIG. 24, the rear terminal edge of the instant sheet A, has dropped from the creasing drums 23 and 24, with the tray bottom tilted upwardly from the left as indicated by FIG. 24. The rear edge of the instant sheet, in dropping, passes through the light beam, 45 energizing the photoelectric unit and its relay and solenoid 199 withdraws the rollers 196 and 197 from the respective cams 181 and 180, or otherwise puts the cams out of action as far as tilting of the floor of the tray is concerned.

In this connection it will be apparent that the solenoid device or devices can actuate and deactivate clutches controlling the rotation or non rotation of the respective cams with the respective shafts, either in augmentation or in 50 substitution of the transverse movement of the cam rollers 196 and 197. It will further be obvious that in lieu of the electrical system disclosed, a purely mechanical system can be effected and operated by auxiliary cams similar to cams 180 and 181 impinging upon operator link- 55 75

ages connected to fingers 147 and 148. In this organization it will be understood that the fingers 147 and 148 are spring biased upward with cams 180 and 181 so as to restrain them downward through the operating linkages, which are constrained essentially, substantially radially of drums 23 and 24. Thus, in the alternate tilting of the fingers 147 and 148, the upward bias is overcome, alternately, by their respective cam-operator mechanism. Since in every case this alternate tilting is closely timed to all other functions of the apparatus, means must be provided for momentarily stopping the finger tilting motion, however attained, in order to permit the establishment of the first or second cross fold. This control may be a cam on the single revolution cross fold cam shaft, or any linkage of the cross fold traversed, whereby to cause latches to hold down the fingers 147 and 148 during the time the cross fold mechanism is operative, disposed for release of the fingers immediately thereafter to continue their synchronized tilting.

At any rate, as shown in FIG. 25 the accordion folded sheet has been deposited in planar disposition on the then quiescent fingers 147 and 148. It will be recognized that at this stage, although the successive panels have been folded upon each other, they may not be in more than an approximation of mutual parallelism, so that the accordion folded rudimentary packet may be of spread thickness, or thickness dimensions, greater than is most compatible with successive accurate cross folds. It is therefore desirable to exert compressive force on the rudimentary accordion folded packet. To this end as diagrammatically illustrated in FIGS. 26 and 26a, a cam 230 is provided on a shaft 231, driven in rotation by the electromagnetically actuated single revolution clutch controlled by the re-energization of the photoelectric device 171 when the reestablishment of the beam from radiant source 170 is effected by the dropping of the last accordion panel from the drums 23 and 24, indicated by FIG. 24, or by completely mechanical means synchronized with and driven by the cross fold cam shaft. The cam 230 in its coordinated timed progress pushes up on roller 232 of a link 233 pivoted to arm 135 on shaft 133. The control arm 136 of shaft 134 is oppositely actuated by a cross link 234 connected to a lever arm 135' on shaft 133, to the end that shaft 133 is oscillated counterclockwise as shaft 134 is oscillated clockwise (and vice versa), and the respective sets of pins 138 and 140 are turned in upon the accordion folded sheet on the tray, to give same a final vertical squeeze to place the panels in intimate parallel relation, preparatory to cross folding same. The continuation of rotation of cam 230 sequentially elevates the respective sets of pins 138 and 140 as the roller moves down from the peak of the cam.

Referring to FIG. 19, a partially schematic vertical section through the housing support is shown, comprising a rear view into the apparatus, with cams and control devices for the feeds, and for effecting accordion folds, omitted. The respective drums 23 and 24 are shown with panel A4 of a sheet A, being delivered downwardly behind drum 23 and in front of drum 24, toward the tray organization which has last been described. For illustrative purposes the tray bottom is shown as mounting two sets of downward feed rolls, respectively 150 and 151, which have been described, and a second exactly similar set 150' and 151' in predeterminedly spaced relation from feed rolls 151 and 150. It will be remembered that for illustrative purposes the width of the instant sheet across leading edge B is even multiples of 8½ inches. With the sheet 17 inches wide, the bottom feed and creasing rolls 150 and 151 are disposed with relation to the laterally guided edge C of the sheet, so that, allowing for slippage, the center line of contact between rolls 150 and 151, is 8½ inches from said edge. This may be designated as a minor distance or spacing.

For sheets 34 inches wide the second set of bottom feed and creasing rolls 150' and 151', with due allowances for slippages, are centered a distance of 17 inches from said laterally guided edge C of the sheet A. This may be designated as a major distance or spacing. It will be seen that a sheet but 17 inches wide requires but one cross fold symmetrically in the longitudinal center of the accordion folded rudimentary packet, to complete a packet of substantially 11 inches by 8½ inches. To this end a first guide chute 250 curves downwardly from the bottom of the tray to the left of crease feed roll 151, to termination at the rear delivery chute.

It will be understood, however, that a sheet 34 inches in width requires two cross folds to produce a packet of the required substantially 11 inches by 8½ inches. With a sheet of 34 inches in width, it will be seen that the first cross fold takes place at a line spaced the major distance (illustratively, as noted, 17 inches) from the side edge C, which happens to locate the first cross fold symmetrically in the longitudinal center of the accordion folded rudimentary packet. The sheets A, as later explained, are either of minor width or of major width.

The symmetry happily attained with sheets of widths which are even multiples of the basic datum dimension, as just discussed, is of no particular importance. What is important is that whatever the relation of the first cross fold to the full longitudinal extent of the rudimentary packet, it must bear a predetermined space relation, either major or minor, to the side edge C, of the instant panel only, which is either the standard datum size for which the apparatus is initially organized, say the 8½ inch minor spacing mentioned for sheets of minor width, or of twice this length, in major spacing in wider sheets of major width. Mention has been made of the ability of the apparatus to provide an ultimate folded packet of datum dimensions, regardless of the length of the individual discrete sheets, and also regardless of the widths thereof, within the capacity of the apparatus. If the illustrative standard datum width or one dimension of the ultimate folded packet is 8½ inches, and that of the other dimension is the illustrative 11 inches, it will be understood that a sheet to be handled by the apparatus must be not less than 8½ inches in width, which is quite minimal indeed. With such a sheet, of said 8½ inches which may be characterized as sub-minor in width, the only folding necessary is the accordion folding, the completion of which creates an ultimate packet of datum dimensions, requiring no cross folding whatever. Sheets having widths ranging from 17 inches down toward 8½ inches, characterized as of minor width, require one cross fold in minor spacing from the side edge C, of the sheet. This is only symmetrical of the longitudinal extent of the rudimentary packet if the minor width is exactly 17 inches, otherwise the predetermined 8½ inch length between the side edge C, and the cross fold establishes a front face of datum dimensions longer than the remaining extent of the cross folded packet between the cross fold and the other side edge of the packet. But this differential in size is inconsequential as the shorter extent is hidden behind the front face of proper dimensions.

Relatedly sheets of a width wider than 17 inches (the major width) may be processed according to the illustrative arrangement of the apparatus. The important thing about the first cross fold in this latter sheet, is that it be the major distance from the side edge C, regardless of the symmetry of the fold as far as the length of the rudimentary packet is concerned. It is only symmetrical when the major width happens to be exactly 34 inches. In any sheet of major width, therefor the first cross fold establishes a semipacket, the front face of which is a rectangle 17 inches by 11 inches. When the other portion of the semipacket is shorter than the 17 inches of the front face, it makes no difference because it is hidden behind the properly shaped and dimensioned front face.

It will be seen that as the packet formed by the cross folding of a sheet of minor width produces the datum size packet, no additional cross folding is necessary or made. On the other hand, it will be clear that any semipacket formed from a sheet of major width requires a secondary cross fold in the center of the 17 inch dimension of the semipacket, in order to bring the all important face thereof, at least, to the ultimate datum dimensions of the illustrative 8½ inches by 11 inches.

Within the capacity of the apparatus, there may occasionally be a discrete sheet handled by the apparatus which is more than an even multiple of 8½ inches, for instance wider than 34 inches. This width, which may be characterized as a major plus width, is processed just the same as the sheets of major width, after previous creasing at 34 inches from the side edge C by the creasing rib and groove elements 21a and 22a on modified feed rolls 21' and 22' of FIG. 10b. This last creasing establishes a line of crease by which the operator can manually fold the excess width into the packet.

For secondary cross folding it is preferred that three additional creasing feed rolls be provided in generally vertical alignment with and below the second set of bottom crease and feed rolls 150' and 151'. These three rolls comprise rear upper feed roll 251, cooperating with an oppositely rotating front feed and crease roll 252, and the latter is vertically juxtaposed to a lower oppositely driven front crease and feed roll 253. The delivery from the front crease and fold rolls 252 and 253 is toward a second curved guide chute 254, shorter than the first guide chute, so that its lower end 254' is spaced from the delivery chute 8 onto which the dropped or conveyor guided single or double folded packet is delivered.

One form of the essential complementary blade and crease roll devices for effecting the cross folds, in cooperation with the respective sets of crease feed rolls, will now be described. Reference is made to FIG. 19.

On a pair of parallel spaced horizontal guide rods below the tray, respectively 260 and 261 (see also FIGS. 8 and 9), a generally open cam-mounting frame 262 is slidably guided. The frame mounts a motor 263 driving a cam 264. Horizontal guide rods 268 are mounted in the upper part of frame 262, upon which a carriage 265, extending across the tray below same, is horizontally slideable automatically by a lever 266, pivoted to the bottom of the frame 262 and slidably pivoted to the carriage 265, by a slot in its upper end to receive pusher pin 269 in carriage 265, and having a cam roller 267 riding on the periphery of cam 264. The upper part of the frame 262 on each side, beside the tray mounts a horizontal guide cam 270 having a downwardly curved terminal camming surface 271. The carriage 265, has a pair of vertical extensions 272, on each of which a bell crank lever 273 is pivoted at 274. Each bell crank lever has one, lower, arm 275 mounting a cam roller 276 riding guide cam 270—271, and forced thereagainst by a suitable spring 277 surrounding the pivot 274. The other, upper, arm 278 of the bell crank lever 273 mounts an idler feed roll 280, and has a perpendicularly offset terminal blade 161, previously mentioned, of a length between the spaced bell crank levers 273 as to extend across the full width of the compound accordion folded sheet.

In the normal course, during the folding of the sheet and its delivery to and upon the tray, the carriage is maintained in the dotted line position at the left of FIG. 19, so as to hold the roller 280 and blade 161 elevated and out of the path of delivery of the accordion folded sheet to the tray. The position of the frame in FIG. 19 is what may be described as a primary position consonant with the formation of a single cross fold of the rudimentary packet. With the organization as so far described, in FIG. 19, and with the carriage disposed to the left in the dotted line position, upon the reenergization of the phototube device 171, marking the drop of

the rear edge, E, of the last accordion folded panel, the cam 264, is rotated, through an electromagnetically actuated single revolution clutch or similar device, as previously mentioned but not shown, and moves away from roller 267, and in response to suitable spring bias 282 against the lever 266, the carriage is forced forwardly toward the full line position of FIG. 19, and as it thereafter reaches a limit of its forward movement the roller 276 rides downwardly on curved camming surface 271 and the arm 278 swings down bringing the blade 161 against the rudimentary packet, forcing a fold therein which is forced against and drawn between the crease feed rollers 150 and 151, and synchronously forces the idler feed roller 280 against the rudimentary packet and assists in feeding sheet material into the fold. In cases where an 11 inch wide sheet is accordion folded and delivered to the tray, roller 280, upon actuation of the cross fold mechanism, grips the end of the rudimentary 11 inch wide packet between itself and constantly rotating crease roller 151 causing the packet to advance edge first longitudinally transversely of the tray and about the contoured near surface of blade 161 feeding downwardly to discharge through crease feed rollers 150 and 151 without creasing the packet. It will be understood that if desired an additional idler roller can be mounted on the lever arm 278 on the other side of the blade 161 to facilitate the feed of the sheet into the cross fold. The cross folded accordion folded sheet is creased by the rolls 150 and 151, and drops onto the first chute 250, by which it is guided to the delivery chute end 8.

It is recognized that it may be desired to make the first cross fold at 17 inches from the side edge C of a wider sheet, as previously mentioned and illustratively, by means of crease feed rollers 150' and 151'. To this end a lever 288 pivoted to the frame at 283, through a complementary pin and slot connection, is pivoted to the carriage 262, and mounts a cam roller 284 biased by a spring 287 against a cam 285 rotatable on a shaft 286. With the carriage retracted to the left to the dotted line position of FIG. 19, and with a wider sheet being deposited in the tray, by suitable control means actuated by the operator, or by automatic photoelectric or mechanical device selection, in accordance with the known width of sheet to be folded, after the drop of the rear end E of the last accordion folded panel (illustratively panel A6), cam 285 rotates from behind roller 284, and the spring 287, pulling on lever 288, pulls the entire frame 262 forwardly to the position indicated in dotted lines at the right side of guide rod 260 in FIG. 19. Synchronously therewith the cam 264 rotates from behind roller 267, sliding the carriage 265 forward and in due course the transverse cross fold blade 161 impinges against the rudimentary packet 7, forcing a crease fold 3 into crease feed rolls 150' and 151'. These rolls both crease and downwardly feed the first cross folded rudimentary packet 6. The delivery thereof, as indicated by the folded packet 6 extended downwardly for illustrative purposes in FIG. 19, is between complementary rear feed roll 251 and upper front feed roll 252. This may be facilitated by additional guides, shown (at 259 in FIG. 19a), to steer the advancing first cross fold 3 into the feed rolls 251—252.

In order to effect the second cross fold on line 4, a lever 290 is pivoted to the frame at 291 on each side of the tray and each mount a cam roller 292 suitably biased against a cam 293 rotatable with a shaft 294. At its outer free end the levers 290 mount a transverse crease blade 295. In due cyclic progression of the components, and with downward feed of the first cross folded rudimentary packet to the proper point, the cam 293 forces the blade 295 generally horizontally across the line of downward feed, forming second cross fold crease 4 and forcing the folded sheet laterally against and drawn between crease feed rollers 252 and 253, simultaneously completing the crease fold 4 and progressing the double cross folded sheet through the 75 rolls 252 and 253 to ultimate delivery to the second chute

254, from which it is delivered gravitationally (or with mechanical conveyor assistance not shown) to chute 250, and slides into rear delivery chute portion 8. Such a completed double cross folded packet is schematically indicated in delivery chute 8, as well as being shown in FIG. 5.

It will be apparent that the disclosure of FIG. 19 is purely illustrative, and that other and simpler forms of mechanism can be availed of to effect similar functions. Reference is made to FIGS. 19a and 19b for an alternate and presently preferred embodiment of cross folding mechanism. This organization is simpler than that of FIG. 19 in that the double carriage configuration is eliminated and a double translation cam is substituted, whereby the operator, or the apparatus automatically, selects, electrically or mechanically, the desired function of the cam to coordinate the cross folds to the width of the sheet being folded. In these figures both the first and the second cross fold is similar to that effected in FIG. 19.

Suitably supported on the frame 10 are side rails 329 adjacent to the tray bottom surface 129. A pair of elongated transversely spaced parallel guide rods 368 are fixed to the frame and extend across and beyond the first pair of downward crease rolls 151 and 150. Carriage member 365 is slidable on the guide rods, and on standards 372 thereon pivotally mounts bell crank levers 373, having upper arms 378 terminating in their outer free ends in the transverse cross blade 161' and roller 380, similar to the related structure of FIG. 19. The bell crank levers 373 have lower arms 375 respectively mounting cam rollers 376, and the bell crank levers are biased downwardly by springs 377. A compound upwardly presenting guiding cam element is provided against which the respective cam rollers 376 engage. The guide cam element is of special construction in which a cam groove is opened or bridged according to whether the blade 161' is to force the semi-packet into downward crease rolls 151-150 or into the second set of downward crease rolls, 151'-150'. While this selective engagement may be accomplished by various means, one illustrative configuration for the purpose is shown in FIG. 19a. Fixed rear primary guide cams 370, having inward and downwardly curved camming surfaces 371, are mounted on the framework, and spaced longitudinally therefrom and attached also on the framework, are mounted secondary guide cams 380', having at their terminal ends downwardly curved camming surfaces 382, and at their forward ends curved surfaces 381 complementary to surfaces 371 of cams 370, so spaced that surfaces 371 and surfaces 381 define downwardly curved cam grooves 384 of proper width to receive and guide the cam rollers 376.

Control plates 383, attached slidably to primary guide cam elements 370, so vertically constrained that their upper surface is coincident in elevation with the upper surface of primary guide cam elements 370 and coplanar with the upper surface of secondary guide cams 380', can be translated horizontally to bridge cam grooves 384, preventing the cam rollers 376 from entering the cam grooves 384, or retracted horizontally to permit such groove traversing passage of the cam rollers.

While, of course, the attitude of the slide plate 383 to control the opening or closing of the cam groove 384 can be changed in any desired manner, such as by any suitable mechanical linkage coordinated with the translational cam selection, for instance, it may be accomplished by the mechanism disclosed. Illustratively, levers 390 are provided, pivoted suitably to the frame or frame extension at 391, and having lost motion pivotal connections to the plate 383 at one end, as at 392. A link 393 is pivoted to the lower end of the lever 390 and to a solenoid actuating device 394. The lever is suitably biased by a spring 393 urging the plate in one direction against the solenoid action.

A double translational cam is provided comprising a short throw cam 396, of long radius, and a long throw cam, of short radius, 397, mounted in adjacency on a shaft

398 and the latter is suitably clutched to a power source to effect a single rotation when energized. The respective cams 396 and 397 have a common radius at their stopped position. A lever 400 is pivoted at its lower end at 401, to the frame, and at its outer free end has a slotted lost motion pivotal connection to a pin 402 in the lower portion of the carriage 365. The lever 403, by a bracket 403 (FIG. 19b), slidably mounts a grooved axle 404 on which is journaled a cam roller 405 of such width as to ride selectively on one or the other of the cams 396 or 397, according to the axial positioning of the axle 404. A spring pressed detent 406 is mounted in the bracket 403 to engage resiliently against groove 407 or groove 408 of the axle to hold the axle in either of two attitudes according to the setting of the cam roller 405. The axle is controlled in position by an illustrative spring-pressed solenoid device 410. The solenoid 410 and the solenoid 394 are controlled in synchronism.

It will be seen that in the normal operation, during the accordion folding, the double cam, 396-397, is in its position of rest, the roller 405 is aligned with the common high point of both double cams, the lever 400 has been pivoted by the cams to its extreme counterclockwise position, as shown in full lines in FIG. 19a, the bellcrank levers 373 have been moved upwardly and to the left so that the blade 161' is out of the path of the sheet as the accordion folds are developed and deposited on the tray. If the sheet is of minor width and but one cross fold is to be effected, the solenoid 394 is actuated in the proper sense to move plate 383 to that attitude at which the cam groove 384 is open. The solenoid 410 is suitably actuated to place the roller 405 on the short throw cam 396. In synchronism with the deposit of the last panel of the sheet on the tray the shaft 398 is given its single fast revolution, the roller 405, riding on the cam 396 permits the carriage 372 to move to the right, under the tension of spring 411 moving the carriage 365 to the first dotted line position shown, at which the cam rollers ride downward about cam surfaces 371, in grooves 384, to effect the proper cross fold.

On the other hand, if the sheet is of major width, illustratively the operator pushes a button or the like, or preferably an automatic photoelectric device to be described is operated and simultaneously properly actuates solenoids 394 and 410. Starting from the position of the full lines of FIG. 19a, the solenoids 304 and 410 function respectively to close the grooves 384 and shift the roller 405 to the long stroke cam 397. When the accordion folded sheet is deposited in the tray the carriage traverses to the right to the second dotted line position shown in FIG. 19a, and the cross fold is accomplished by the downward crease rolls 151' and 150'. The remainder of the apparatus, for guiding and effecting the second cross fold is similar to and bears the same reference characters as those in FIG. 19.

Automatic selection of carriage traverse in accord with sheet width in the presently preferred electrically actuated form, as disclosed in FIGS. 13 and 19, consists of light source 470 directed across the path of the oncoming instant sheet, a distance just in excess of the widest sheet of minor width to be cross folded by cross fold crease rolls 150-151, illustratively 17½ inches from the position of edge C of sheet A when the latter has been delivered, accordion folded to tray 147-148, toward photoelectric receiving element 471. If oncoming sheet A is an illustrative 17 inches or less in width, the light beam from 470 to 471 is not intercepted by said sheet and the associated photoelectric control relays remain in their normal position, maintaining carriage traverse cam bridge controlling solenoid 394 and traverse cam selector solenoid 410 in their correct attitude for cross folding by rolls 150-151. Introduction of a wider sheet to the machine illustratively more than 17½ inches in width, causes the light beam to be intercepted before impinging upon photoelectric receptive element 471 thus actuating the associated photo-

electric control relays, shifting the attitudes of solenoids 394 and 410 and thus automatically causing a cross fold to be made by cross fold rollers 150'—151'. The adoption of this disclosure insures a machine automatic to the extent of accepting successively, in random sizes, any sheets within the capacity of the machine without adjustment or selection on the part of the operator.

It will be apparent, as noted, that there may be an occasional sheet to be folded, which is not in width an even multiple of $8\frac{1}{2}$ inches. In case the excess over such multiple is a few inches, it may be preferred to utilize the modification of the feed rolls indicated in FIG. 10b. In this modification the upper feed roll 21' and lower feed roll 22' mount complementary crimping beads and grooves, respectively 21a and 22a, mounted on the rolls at a spacing from the guided edge of the sheet which is an even multiple of the illustrative $8\frac{1}{2}$ inches. In the event that the sheet is of a width in excess of such even multiples, which generally is the unusual case, the passage of such sheet through the apparatus finds it transversely crimped along a fold line established by the rib and groove. Although at this juncture this line is not a complete fold, it is so established in the sheet that a simple manual manipulation by the operator can complete the actual fold of such excess material.

Referring to the diagrammatic figures, from FIG. 27 to FIG. 32 inclusive, in successive or related stages of sheet progress for further explanation of the operation of the apparatus, so far as certain phases thereof are concerned, an exemplification of said operations are disclosed. Although shown in reverse of other figures, FIG. 27 represents any given rotational situation of the drums 23 and 24 at the time the treadle 14 is first depressed. At this juncture the upper primary feed roller is elevated and held elevated by the cam roller 75 in its relation to cam 70, and the instant sheet A is positioned against stop 16, and overlies and extends partially beyond the rotating lower primary feed roll 13.

FIG. 28 represents the starting position, in which, with concurrence of the permitting factors, the upper feed roll 12 has dropped, stop 16 has been downwardly withdrawn, and feed roll 12 has initiated the inward feed of the positioned and previously stopped sheet, toward feed rolls 21 and 22.

In FIG. 29 the advancing sheet A has passed between the feed rolls 21 and 22 and its leading edge B has entered between and been gripped by drums 23 and 24, with blade 32 of drum 23 held against radial advance, and the roller 12 has been elevated to its normal inoperative position.

FIG. 30 represents the next succeeding position of the coordinated parts and of sheet A, in which the advancing edge B of the sheet has advanced beyond the drums 23 and 24, and the latter have turned 180° from the position shown in FIG. 29, the blade hold-out is inoperative, and the blade 32 of the drum 24 has been extended to force fold 1 into the crease rolls of drum 23.

FIG. 31 represents the same attitude of the parts shown in FIG. 30, but showing the beginning of the sector gear motion to rotate the crease rolls of upper drum 23 to crease and draw in the fold on line 1.

FIG. 32 represents the situation of FIG. 30, with the illustrative lockout lever in its innocuous offset position permitting the blade to advance to form the first accordion fold.

FIG. 33 represents the situation of the illustrative blade hold-out lever in the advancement of the sheet as shown in FIG. 29, with the blade 32 held against creasing engagement against the short area or tab of the sheet engaged by the drums 23 and 24.

It will be clear that many modifications, alterations and substitutions of parts can be made in the invention without departing from the spirit thereof, and all such are to be construed as within the scope of the invention herein disclosed and claimed.

I claim as my invention:

1. Apparatus of the class described, comprising a folded sheet-receiving tray, means effecting plural accordion folds in a discrete sheet and depositing it gravitationally in successive panels on said tray following a general path between the means and said tray, movable folding means having a first position in which it is normally out of the path of such panels during the deposition, and means operative after the accordion folding of the sheet is completed moving said movable folding means across said path substantially parallel to the folded sheet and over the deposited panels to a general second position, and means moving said movable folding means in its general second position transversely of and against said panels effecting a cross fold.
2. Apparatus of the class described for folding discrete sheets of random lengths each having a transverse leading edge, comprising a support means for transitorily mounting sheets with the leading edges of each successive sheet in a predetermined position on the apparatus, transitorily operative mechanism engaging and feeding respective individual sheets transversely of its said leading edge, substantially continuously operating means imparting successive oppositely directed spaced accordion folds to each sheet delivered by said mechanism with each fold parallel to the leading edge of the instant sheet, operator-controlled means initiating the operation of said mechanism, and interconnection between the said mechanism and the substantially continuously operating means, whereby each operation of said mechanism is integrated with the operation of said substantially continuously operating means so that the first fold in any instant sheet is at the same predetermined distance from its said leading edge, said apparatus being arranged whereby, without change thereof, all other folds are spaced apart substantially the same distance as that between the leading edge and the said first fold, continued throughout the length of the sheet regardless of the varying respective lengths of instant sheets.
3. Apparatus of the class described comprising a pair of juxtaposed continuously driven drums having a general line of peripheral intersection, each drum comprising a radially extensible blade and a pair of complementary juxtaposed oppositely rotatable creasing rolls, means cyclically rotating said crease rolls in one relative direction followed by rotation of said crease rolls in the other relative direction, means cyclically thrusting said blade of one drum when substantially aligned with said crease rolls of the other drum and then retracting same during such substantial alignment, and means feeding a sheet to the said general line, whereby the blade on one drum thrusts the sheet toward the creasing rolls of the other drum, wherein the creasing rolls draw in and crease the sheet, and upon reversal of rotation of the crease rolls the crease is ejected effecting an accordion type of folding of said sheet, in which the first fold of any sheet is at a predetermined distance from the leading edge of such sheet, defining a first panel in said sheet, in which the leading edge of such sheet in the advance of the latter passes beyond the said general line in an interval of predetermined angular relation thereof at which one blade of one drum becomes transitorily juxtaposed to complementary crease rolls of the other drums across an instant sheet at a line within said first panel, and means precluding the radial extension of said one blade of said one drum during said interval to prevent a misplaced first fold in said sheet.
4. Apparatus of the class described comprising a housing enclosure, means on the enclosure defining a sheet entrance, a support adjacent to said entrance, lateral sheet guide means on said support, a driven lower primary feed roller in said enclosure adjacent to said entrance, a pair of driven complementary secondary feed rolls in the enclosure, vertically movable stop means in the enclosure normally in the line of a sheet positioned on said support between said lower primary feed roller and said second-

ary feed rolls whereby a sheet can be mounted stationarily with its front end in said entrance overlying said lower primary feed roll and having its front edge in general abutment against said stop means and a side edge engaging said lateral sheet guide means, bracket means pivoted in the enclosure, an upper primary feed roll pivoted on the bracket means above said lower primary feed roll, means normally holding said bracket means in one angular position on its pivot whereby said upper primary feed roll is spaced upwardly from said lower primary feed roll to admit such sheet to abutment against said stop means, driven sheet folding means in said enclosure having cyclic progression and to which a sheet is fed by said secondary feed rolls, manual trigger means operated transitorily at any point in the cyclic progression of the driven sheet folding means, and means responsive to actuation of the manual trigger means only when the driven sheet folding means is in a predetermined state of cyclic progression moving said bracket and thus said upper primary feed roll downward to contact with such sheet and synchronously moving said stop means transitorily out of the line of such sheet and moving such sheet inwardly of the enclosure to feeding engagement with said secondary feed rolls, whereby the first accordion fold of any sheet is a predetermined distance from its front edge.

5. Apparatus as in claim 4, said sheet folding means comprising a pair of juxtaposed oppositely driven drums having a general line of peripheral intersection toward which a sheet is fed by said secondary feed rolls, each drum comprising a radially extensible blade and a pair of complemental juxtaposed oppositely rotatable creasing rolls, means rotating said crease rolls to crease and draw a sheet portion inward of the instant drum and then rotating same to expel said portion from said drum cyclically functional with the rotation of each instant drum, means cyclically functional with the rotation of each instant drum extending and retracting its blade whereby with a sheet passing across said general line the blade on one drum creases a sheet and forces the crease against the creasing rolls of the other drum to effect an accordion type of fold of such sheet.

6. Apparatus as in claim 5, comprising fixed internal cams juxtaposed to each end of each drum and having a single internal cam fall, means biasing each instant blade outwardly of its instant drum, cam roller means on each blade riding the internal surfaces of said fixed cams whereby the blade is extended and retracted once in each revolution of the instant drum, and supplemental means operative once in each cycle of sheet feed precluding extension of the blade.

7. Apparatus as in claim 6 in which said supplemental means is movable to intersect the cam roller means to prevent it from moving on said cam fall of said fixed cam.

8. Apparatus as in claim 5, comprising fixed internal cams juxtaposed to each end of each drum and having a single internal cam fall, means biasing each instant blade outwardly of its instant drum, cam roller means on each blade riding the internal surfaces of said fixed cams whereby the blade is extended and retracted once in each revolution of the instant drum, supplemental means operative once in each cycle of sheet feed precluding extension of the blade, in which said supplemental means is movable to intersect the cam roller means to prevent it from moving on said cam fall of said fixed cam, means normally inoperative during the time that the upper primary feed roller is elevated, and means mechanically responsive to the dropping of said upper primary feed roller to the sheet superposed on the lower primary feed roller for moving said means to intersect the path of movement of the cam roller relative to said fixed cam to preclude the said roller from moving on said cam fall.

9. Apparatus of the class described comprising a support, a lower driven primary feed roll, bracket means pivoted to the support, an upper primary feed roll journaled in the bracket means generally above said lower

5 feed roll, sheet folding means mounted on said support and comprising a pair of oppositely driven juxtaposed drums, mutually complemental creasing and folding elements on the respective drums operative on a sheet fed between said drums, a primary feed controlling cam fixed to one of said drums and having a cam surface formed of surfaces of different radii connected by sloping surfaces respectively comprising cam rise and cam fall surfaces, said bracket means mounting a cam roller riding on said cam, said cam rise and fall surfaces of said cam having predetermined angular relation to the respective creasing and folding elements of the drum mounting the cam so that at a predetermined point in the angular progress of said last mentioned drum the cam roller moves from the surface of one radius to that of a different radius whereby the bracket means moves on its pivot to move the upper primary feed roll against the lower feed roll to impart feeding pull to a sheet superposed on said lower feed roll with pressure maintained until the cam roller again moves to the surface of said one radius and the upper feed roller is elevated by the bracket means.

10. Apparatus of the class described comprising a support, a lower driven primary feed roll, bracket means pivoted to the support, an upper primary feed roll journaled in the bracket means generally above said lower feed roll, sheet folding means mounted on the support and comprising a pair of oppositely driven juxtaposed drums, mutually complemental creasing and folding elements on the respective drums operative on a sheet fed between said drums, a primary feed controlling cam fixed to one of said drums and having a cam surface formed of cams of different radii connected by sloping surfaces respectively comprising cam rise and cam fall surfaces, said bracket means mounting a cam roller riding on said cam, said cam rise and fall surfaces of said cam having predetermined angular relation to the respective creasing and folding elements of the drum mounting the cam so that at a predetermined point in the angular progress of said last mentioned drum the cam roller moves from the surface of one radius to that of a different radius whereby the bracket means moves on its pivot to move the upper primary feed roll against the lower feed roll to impart feeding pull to a sheet superposed on said lower feed roll with pressure maintained until the cam roller again moves to the surface of said one radius and the upper feed roller is elevated by the bracket means, and latching means adjacent to said bracket means holding said bracket means in such attitude relative to its said pivot that said upper primary feed roll is held elevated without regard to cyclic progression of said cam, and means controlled by an operator for unlatching said latching means to effect descent of said upper primary feed roll with said bracket means operative only when said cam attains a predetermined angular relation.

11. Apparatus of the class described comprising a support, a lower driven primary feed roll, bracket means pivoted to the support, an upper primary feed roll journaled in the bracket means generally above said lower feed roll, sheet folding means mounted on the support and comprising a pair of oppositely driven juxtaposed drums, mutually complemental creasing and folding elements on the respective drums operative on a sheet fed between said drums, a primary feed controlling cam fixed to one of said drums and having a cam surface formed of cams of different radii connected by sloping surfaces respectively comprising cam rise and cam fall surfaces, said bracket means mounting a cam roller riding on said cam, said cam rise and fall surfaces of said cam having predetermined angular relation to the respective creasing and folding elements of the drum mounting the cam so that at a predetermined point in the angular progress of said last mentioned drum the cam roller moves from the surface of one radius to that of a different radius whereby the bracket means moves on its pivot to move the upper primary feed roll against the lower feed roll to impart

feeding pull to a sheet superposed on said lower feed roll with pressure maintained until the cam roller again moves to the surface of said one radius and the upper feed roller is elevated by the bracket means, and a cam mounted on said one drum having cam surfaces of respectively large and small diameters connected by sloping cam rise and cam fall surfaces, a detent lever pivoted to the frame and biased toward said cam, said detent lever mounting a cam-reacting device riding on the cam, said detent lever having a detent portion engageable with said bracket means to hold said upper primary feed roll in its elevated position to restrict control of the lowering of said bracket means to the proper slope of said primary feed controlling cam assuring the start of the paper feed at the correct instant in the cyclic progression of the machine, said detent lever disengageable from said bracket means when the device rides on one of said sloping surfaces in synchronism with the release of the bracket means for dropping said primary upper feed roll by change of relation of the cam roller on the bracket means to the surface of said primary feed controlling cam.

12. Apparatus of the class described comprising a tray, means folding successive discrete sheets with successive oppositely directed panel-defining accordion folds of which the first fold is in the same direction in each such sheet and delivering same in successive panels in a general line path to said tray, a first panel of each such sheet defined between the leading edge of the sheet and the first of such folds, with each such first panel of the same predetermined width in each successive discrete sheet, the said first panels as delivered having gravitationally induced angular divergence from the second panel so that the leading edge of said first panel is the first portion of any discrete sheet to contact said tray, said tray comprising an effective surface having a planar position which is generally horizontal and an effectively tilted position relative to the horizontal in which it is acutely divergent from the leading edge and the adjacent portion of the delivered first panel to guide said first panel into parallelism with said tray.

13. Apparatus of the class described comprising a tray, means folding successive discrete sheets with successive oppositely directed panel-defining accordion folds of which the first fold is in the same direction in each such sheet and delivering same in successive panels in a general line path to said tray, a first panel of each such sheet defined between the leading edge of the sheet and the first of such folds, with each such first panel of the same predetermined width in each successive discrete sheet, the said first panels as delivered having gravitationally induced angular divergence from the second panel so that the leading edge of said first panel is the first portion of any discrete sheet to contact said tray, said tray comprising an effective surface having a planar position acutely divergent from the leading edge and the adjacent portion of the delivered first panel, to guide said first panel into parallelism with said tray, in which said generally horizontal position is a first position, and such tilted position is a second position, and means for moving said tray from its second position toward the horizontal as the accordion folded sheet is lowered.

14. Apparatus of the class described comprising a tray having an effectively planar surface and first and second lateral stops on respectively opposite sides thereof, said effective surface lying normally in a substantially horizontal plan, means effectively tilting said effectively planar surface in one direction into a first position in angular relation to the horizontal, and effectively tilting said effective planar surface in the other direction into a second position in angular relation to the horizontal in cyclic alternation, means cyclically folding successive discrete sheets with successive oppositely directed panel-defining accordion folds of which the first fold is in the same direction in each such sheet and delivering same in successive panels to said tray, a first panel of each such sheet defined between the leading edge of the sheet and the first of such

folds and as delivered having gravitational divergence from the second panel so that the leading edge of the sheet is the first portion of any discrete sheet to contact said tray, and means synchronizing the delivery of the accordion folded sheet and the means effectively tilting and moving the effective planar surface of the tray into its said first position in which said surface is in acute angular relation to the first panel to receive and guide said first panel on the tray within a first lateral stop and in synchronism with said delivery to effectively tilt the effective planar surface to its second position at which the surface is in acute angular relation to the second panel of a sheet to receive same within an opposite second stop.

15. Apparatus of the class described for folding any given discrete sheet, of a series of discrete sheets each of relatively random lengths and each of relatively random widths within the capacity of the apparatus, into a folded packet of fixed predetermined edge dimensions, said random widths comprising a first group of sheets of minor widths within a predetermined range of minor widths, and a second group of sheets of major widths within a predetermined range of major widths, comprising a support, folding means on the support, means feeding an instant discrete sheet to said folding means, said folding means imparting successively oppositely directed spaced transverse accordion folds to a discrete sheet fed to said folding means continued throughout the length of a sheet regardless of the length or width thereof, means effecting cross folds in the accordion folded sheet, and actuating means comprising sensing means automatically responsive to an instant sheet width and operating the means effecting cross folds and forming cross folds selectively in number according to whether the sheet is of minor or major width, said last means selectively effecting a single cross fold in a sheet of minor width and two successive cross folds in a sheet of major width, in the formation of an ultimate packet of the same predetermined edge dimensions regardless of whether it has one or two cross folds.

16. Apparatus the class described for folding any discrete sheet of a series of discrete sheets, each sheet of such series being potentially of relatively random length and each of relatively random widths within the capacity of the apparatus, into a folded packet of fixed predetermined dimensions, said random widths comprising a group of minor widths within a predetermined range and a group of major widths within a predetermined range, comprising a support, folding means on the support, means feeding an instant discrete sheet to said folding means, said folding means imparting successively oppositely directed spaced transverse accordion folds to a discrete sheet fed to said folding means continued throughout the length of a sheet regardless of the length or width thereof, means effecting cross folds in the accordion folded sheet, and actuating means operating the means effecting cross folds and forming cross folds selectively in number according to whether the sheet is of minor or major width, said last means selectively effecting a single cross fold in a sheet of minor width and two successive cross folds in a sheet of major width, in the formation of an ultimate packet of the same predetermined edge dimensions regardless of whether it has one or two cross folds, in which said actuating means normally operates to effect a predetermined given number of cross folds according to a given group of widths, 65 sensing means juxtaposed to said sheet and signalling a sheet of a different group of widths from that for which the actuating means normally operates, said signal operative upon said actuating means and effecting a different number of cross folds to such sheet.

17. Apparatus of the class described for folding discrete sheets of random respective lengths and of respectively minor and major widths into a packet of predetermined dimensions, comprising a support, means on the support imparting successive oppositely directed transverse accordion folds to a discrete esheet forming panels

of which the first of any given discrete sheet formed between the leading edge of the sheets and the first transverse fold is of predetermined width defining one dimension of an ultimate folded packet, said panels in stacked assembly after folding forming a rudimentary packet, means automatically selectively operated effecting a cross fold in a sheet of minor width in a first rudimentary packet at a predetermined minor distance from an edge of such rudimentary packet defining the other dimensions of and completing a packet of the said predetermined dimensions, said means automatically selectively operated effecting a cross fold in a second rudimentary packet at a predetermined major distance from said edge of such sheet forming, a second semipacket in sheets of major width, said major distance being twice the length of said minor distance, and supplemental means effecting a second cross fold in the second semipacket at said predetermined minor distance from an edge forming a complete packet whereby all packets regardless of variations of sizes of respective sheets have identical lateral edge dimensions.

18. Apparatus of the class described comprising means for folding and delivering a sheet in successive oppositely directed folds defining a plurality of panels, a tray in the line of delivery of said folded sheet, said tray comprising a pair of parallel spaced shafts, a series of spaced fingers mounted on each of said shafts, said respective fingers being in mutually staggered relation so that from mutual general planar relation oscillation of one of said shafts moves its mounted fingers about the axis of the said one of said shafts to effectively tilt the bottom of the tray to inclination toward said one shaft to facilitate planar disposition of a panel thereon, and means for tilting said one of said shafts.

19. Apparatus of the class described comprising a support, a first and a second driven drum journaled for opposite rotation relative to the support, said drums having a line of peripheral intersection, each drum mounting a radially extensible blade and a pair of spaced crease rolls, each of said blades mounting a cam reacting surface, fixed cams having internal cam surfaces disposed on the support so that the respective cam reacting surfaces ride thereon during the rotation of the respective drums, each of said internal cams having a cam fall and rise surface adjacent to said line, the angular relation of the respective drums being such that when the blade of one drum is substantially juxtaposed to said line the blade of said other drum is 180° away from said line, an element pivoted to the support on an axis between said cams, said element being oscillatable between two positions, said element having lateral surfaces which diverge toward the pivot and lead into recesses, each recess being of such contour as to at least partially register axially of said pivot with the fall and rise surfaces of the instantly juxtaposed internal cam, said element in one position on its pivot receiving the cam reacting surface of one blade in its said recess and incident to pressure therefrom due to rotation of the drum on which said one blade is mounted moving on its said pivot to force said blade reacting surfaces inwardly out of the fall and rise surface to entry upon the internal cam surface of the instant cam.

20. Apparatus as in claim 19, in which said element is positioned on its said pivot in movement pursuant to intersection of the cam reacting surface of one blade with a surface of the element to position the latter so that the instant cam reacting surface enters the recess with which the instant surface communicates to force the cam reacting surface of the instant blade outwardly of the fall and rise surfaces of the instant internal cam surface.

21. Apparatus of the class described comprising means for folding and delivering a discrete sheet of a series of discrete sheets of random lengths in successive oppositely directed transverse folds defining a plurality of panels, a tray to receive said delivered folded sheet comprising

a pair of parallel spaced shafts each parallel to the line of accordion fold of such sheet, a finger on each of said shafts, said fingers being in mutually staggered relation axially of the shafts and defining a tray surface, means oscillating said respective shafts in cyclic synchronism with the means for folding and delivering between a first position in which the respective fingers lie in a common substantial plane and a second position in which said fingers are in angular relation to such plane in order to facilitate delivery of the respective panels of the folded sheets, whereby each delivered panel is guided into parallelism with said tray.

15 22. Apparatus as in claim 21, in which said means oscillating oscillates the shafts in alternation according to the direction of delivery of the successive panels from said folding and delivering means.

20 23. Apparatus as in claim 21, and means controlling the means oscillating so that the respective shafts oscillate continuously during delivery of the folded sheet to the tray and the oscillations are stopped with the fingers in the said first position when the delivery has been completed so that the panels are disposed in generally planar relation on said tray.

25 24. Apparatus as in claim 23, and a supplemental shaft, a pin on said shaft generally radially thereof, means for oscillating said supplemental shaft between a normal position in which said pin is generally vertical and an operated position at which said pin is generally horizontal and overlies said tray, and control means operated only after all of the panels of such discrete sheet have been disposed in generally parallel relation on the tray in its first position actuating said last mentioned means for oscillating and moving said supplemental shaft to force the pin against the delivered folded sheet on said tray.

35 25. Apparatus of the class described comprising means for folding and delivering a discrete sheet of a series of discrete sheets of random lengths in successive oppositely directed transverse folds defining a plurality of panels, a tray to receive said delivered folded sheet comprising a pair of parallel spaced shafts each parallel to the line of accordion fold of such sheet, a finger on each of said shafts, said fingers being in mutually staggered relation axially of the shafts and defining a tray surface, means for oscillating said respective shafts in cyclic synchronism with the means for folding and delivering between a first position in which the respective fingers lie in a common substantial plane and a second position in which said fingers are in angular relation to such plane in order to facilitate delivery of the respective panels of the folded sheets, whereby each advancing panel is guided into parallelism with said tray, means controlling the means oscillating so that the respective shafts oscillate continuously during delivery of the folded sheet to the tray and the oscillations are stopped with the fingers in the said first position when the delivery has been completed so that the panels are disposed in generally planar relation on said tray, in which said control means includes a photoelectric device, means projecting radiant energy upon said device below said means for accordion folding,

from a vertical position out of the path of said formed and delivered panels of a sheet to a compressing attitude generally parallel to said tray surface in its definition of a tray surface in its said first position, and means responsive to the said reenergization of said photoelectric device pursuant to the stoppage of said first mentioned shafts with the said first mentioned fingers in their said first position energizing said second pair of supplemental shafts to move said compressing fingers against the panels on said tray to compact same.

27. Apparatus as in claim 25, and a supplemental shaft, a generally radially extending pin on said supplemental shaft, said supplemental shaft movable between a normal position in which said pin is generally vertical and an operated position in which said pin is generally horizontal and overlies said tray, means for imparting a single oscillation of said supplemental shaft between said normal position and said operated position and return controlled upon the reenergization of said photoelectric device to press the delivered panels of the sheet against the tray to compress same.

28. Apparatus of the class described comprising means for folding and delivering a sheet in successive oppositely directed transverse folds defining a plurality of panels, tray means to which the folded sheet is delivered, said tray means mounting a pair of oppositely rotating downwardly feeding crease rolls beneath said delivered sheet, a horizontally slidable carriage adjacent to said tray movable longitudinally of the respective panels, a creasing blade movably mounted on said carriage movable with the carriage to a normal position in which the creasing blade is out of the path of delivery of said folded sheet, means moving said carriage from its normal position to an operative substantially creasing position with the creasing blade above said delivered folded sheet, and means forcing said creasing blade downwardly against the folded sheet to force a portion thereof between said downwardly feeding crease rolls, to form a cross fold in said folded sheet.

29. Apparatus as in claim 28, and a second pair of downward feeding crease rolls mounted on said tray means parallel to and spaced from the first, and means for moving said carriage to a second operative creasing position at which said creasing blade forces a portion of the folded sheet between said second pair of downwardly feeding crease rolls, to form a cross fold therein.

30. Apparatus as in claim 29 and a pair of lower oppositely rotating downward feeding crease rolls below said second pair of crease rolls to receive the folded sheet delivered by the latter, a third crease roll juxtaposed to one of said lower crease rolls and rotative oppositely relative thereto to form therewith a pair of transverse feed rolls, a second creasing blade, and means moving the latter against the cross folded sheet delivered between the lower crease rolls to crease the latter and force it between the transverse feed rolls to form a second cross fold in said sheet.

31. Apparatus as in claim 29 and means for delivering a cross folded sheet from either sets of crease rolls to a common delivery point.

32. Apparatus for folding sheets having a maximum capacity as far as sheet widths are concerned, comprising a support, means comprising components automatically imparting successive oppositely directed spaced accordion folds to a discrete sheet supplied to said means continued throughout the length of such sheet regardless of the length or width of an instant sheet, and means automatically responsive to variations in widths of successive instant sheets effecting cross folds in the instant accordion folded sheet selectively in number according to the width of such instant sheet, whereby an ultimate folded packet of substantially predetermined lateral dimensions is established regardless of the length or width of successive instant sheets of varying width within said maximum capacity.

33. Apparatus of the class described for folding discrete sheets of random lengths and of relatively minor and of relatively major different widths, comprising a support, means on the support imparting successive oppositely directed spaced accordion folds to a discrete sheet continued throughout the length of the sheet regardless of the length thereof forming a rudimentary packet, and means automatically selectively operated determining a sheet of minor width effecting a cross fold in a rudimentary packet of minor width at a predetermined minor distance from an edge of said sheet to complete a folded packet of predetermined dimensions, said means automatically selectively operated determining a sheet of major width effecting a cross fold in a rudimentary packet of major width at a predetermined major distance from an edge of said sheet forming a semipacket, and supplemental means effecting a cross fold in the semipacket forming a complete packet of the same predetermined dimensions.

34. Apparatus of the class described, comprising a support, means on the support having an operative predetermined organization including components automatically imparting successive oppositely directed spaced accordion folds to a discrete sheet supplied to said means continued throughout the length of an instant sheet producing an accordion folded sheet automatically without change of said predetermined organization regardless of the length or width of an instant sheet, and means effecting cross folds in accordion folded sheets selectively in number according to the width of an instant sheet between relatively minor widths and relatively major widths and forming a packet of predetermined lateral dimensions regardless of the instant minor or major width of the sheet from which the packet is formed, sensing means on the support signalling the width of an instant sheet, by a signal, said signal operative on said means effecting cross folds and selecting a single cross fold on a sheet of minor width and plural cross folds on a sheet of major width, whereby the selection is an automatic function of the width of such sheet.

35. Apparatus of the class described, comprising a support, a single pair of continuously driven juxtaposed elements on the support, complemental means on the respective elements for cyclically imparting successive oppositely directed spaced accordion folds to a sheet, means for feeding a sheet to said elements, impulse means susceptible to energization for actuating said means for feeding, and control means for delaying the actuation of said means for feeding until the elements are in a predetermined relative position whereby the first accordion fold is of predetermined spacing from the front edge of said sheet.

36. Apparatus of the class described comprising continuously driven rotatable means for imparting successive oppositely directed spaced accordion folds to a sheet cyclically during the rotation of said means, means operable during such rotation for receiving a transitory pulse, means for feeding a sheet to said rotatable means operable in response to such pulse, and control means storing such pulse and preventing operation of said means for feeding until said rotatable means attain such cyclic relation that the first accordion fold occurs in said sheet in predetermined spacing from the front edge of such sheet.

37. Apparatus of the class described comprising means for stationarily supporting a sheet to be folded, continuously operating means for cyclically forming successive oppositely directed accordion folds defining a first panel between the front edge of the sheet and the first accordion fold and a second panel between the first and second accordion folds of substantially similar predetermined widths, control means operable at random with relation to the cyclic progression of said continuously operating means, and means responsive to the control means and to the cyclic progression of said continuously operating means for feeding a previously stationary sheet to said continuously operating means in synchronism with the

cyclic progression thereof whereby said first panel is of said predetermined width.

38. Apparatus as in claim 37 in which the operation of said control means is transitory only as compared with the cyclic progression of said continuously operating means between folds.

39. Apparatus of the class described, comprising a tray, means effecting plural accordion folds in a discrete sheet and depositing the folded sheet in successive panels on said tray, movable means normally out of the path of such panels during the deposition, control means operated automatically as a function of the completion of the panels, and means controlled by said last means successively moving said movable means over the tray-deposited accordion folded sheet substantially parallel thereto in a first phase of movement thereof and then transversely against the deposited panels in a second phase of movement thereof effecting a cross fold in such accordion folded sheet.

40. Apparatus as in claim 39, and a first pair of downwardly feeding crease rolls on said tray in juxtaposition to said movable means during the second phase thereof.

41. Apparatus of the class described, comprising a tray, means effecting plural accordion folds in a discrete sheet in number variable with the length of the sheet and depositing the folded sheet in successive panels on said tray, movable means normally out of the path of such panels during the deposition, control means operated automatically as a function of the completion of the panels, and means for successively moving said movable means over the tray-deposited accordion folded sheet substantially parallel thereto in a first phase of movement thereof and then transversely against the deposited panels in a second phase of movement thereof effecting a cross fold in such accordion folded sheet, a first pair of downwardly feeding crease rolls on said tray in juxtaposition to said movable means during the second phase thereof, and a second pair of downwardly feeding crease rolls on said tray in spaced relation to said first pair, and means automatically responsive to the width of such sheet for controlling said first phase to place either the first or the second of said pairs in juxtaposition to said movable means in its said second phase.

42. Apparatus as in claim 41, and a pair of transversely feeding crease rolls below said second pair of downward feeding crease rolls, and movable means operative relative to a cross folded sheet delivered from said second pair and to said transversely feeding crease rolls, to form a second cross fold in said sheet.

43. Apparatus of the class described for folding a series of discrete sheets of relatively disparate widths ranging from relatively minor widths not greater than a maximum minor width through sheets of relatively major widths greater than said minor width, comprising means for imparting successive oppositely directed spaced accordion folds to a discrete sheet regardless of its length and whether it is of minor or major width to form an accordion folded sheet, and means automatically responsive to the width of respective instant sheets of such series forming one cross fold only in an accordion folded sheet of minor width and forming a first cross fold and then successively a second cross fold in an accordion folded sheet of major width.

44. Apparatus of the class described, comprising a support, means for effecting plural accordion folds in a sheet and depositing it in successive integral panels on said support, movable means having a normal position out of the path of such panels during such deposition in a first relative position of said movable means and said panels, and means including sensing means automatically operative in response to movement of the last panel only toward said support for relatively moving said movable means and said deposited panels and transversely of the deposited panels into a second relative position, and means actuating said movable means in said second relative position for effecting a cross fold in said panels.

45. Apparatus as in claim 44, in which actuation of said movable means in said second relative position establishes a cross fold at a predetermined distance from an edge of said panels, and in which the means automatically operative relatively moves said movable means and said panels into a third relative position at which actuation of the movable means establishes a cross fold in said panels at a greater distance from said edge than said predetermined distance, and sensing means responsive to the width of an instant sheet controlling said means for relatively moving said panels and said movable means selectively for establishment of the second or the third relative positions thereof.

46. Apparatus of the class described, comprising means for folding and delivering a sheet in successive oppositely directed folds defining plural panels, each having an angular relation to the horizontal in delivery from said means for folding, a tray below said means receiving and supporting the folded sheet effectively movable between a substantially horizontal position and tilted positions relative to the horizontal, means for effectively tilting the tray in synchronism with the formation of the respective folds to receive the advancing edge of each delivered panel at an acute angle to the tray to guide each panel to the tray to minimize jamming of the panels of the folded sheet on contact with the tray.

47. Apparatus as in claim 46, and means for cross folding the panels of a complete folded sheet mounted on the tray, and means for compacting the panels of such sheet mounted on said tray after delivery thereto and in the substantially horizontal attitude of the latter prior to cross folding of said delivered compacted panels.

48. Apparatus of the class described comprising a support, a drum journaled on the support, a radially extensible blade mounted on said drum, a cam reacting surface on said blade, a tilting cam element pivotally mounted on the support, means for moving said element in one direction on its said pivot, said element having a sloping lateral edge surface for impingement by said cam reacting surface when in said one position for moving said element toward a second position on its pivot, said lateral sloping surface leading into a recess into which said cam reacting surface enters, and with continued rotation of said drum pressure is developed on a wall of the recess synchronously turning said element on its said pivot and forcing the cam reacting surface of said blade radially inward of said drum.

49. Apparatus of the class described, comprising an apparatus of known dimensions having an entrance slot for a series of discrete sheets of random lengths and of widths not greater than said entrance slot and said series comprising sheets of minor width not greater than a maximum minor width and of major width greater than said maximum minor width, said apparatus comprising means for accordion folding a sheet to form plural panels of substantially similar widths including a trailing edge panel of a width not greater than said similar width variable according to the length of such sheet with relation to the panels to be formed therefrom, and means automatically responsive to the width of an instant sheet cross folding such accordion folded sheet into an ultimate packet of the same predetermined dimensions regardless of the minor or major width of such sheet.

50. Apparatus of the class described comprising continuously driven means for accordion folding an instant discrete sheet of a series of discrete sheets of relatively varying widths, means for supporting said accordion folded sheet, movable means movable relative to the means for supporting between a normal position and one of the two relatively spaced selected second positions of respectively first and second spacings from said normal position, means for moving said movable means relative to such folded sheet comprising a double cam, one cam of which moves said movable means to its position of first spacing and the other cam of which

moves said movable means to its position of second spacing, means for imparting a single rotation to said double cam in response to the completion of such accordion folding, and means operative automatically in response to the instant width of an instant discrete sheet for coupling a selected one of the cams of said double cam to said movable means for predetermining the second position thereof.

51. Apparatus of the class described, comprising a tray, a feed roll on said tray, a supplemental feed roll, means for folding a sheet into a plurality of alternately oppositely directed accordion folds and delivering the folded sheet in a plurality of generally rectangular panels on said tray overlying said feed roll, movable means journaling said supplemental feed roll, said supplemental feed roll movable bodily in translation to contact said panels after delivery thereof to the tray and with the first mentioned feed roll to feed such panels longitudinally of the panels and transversely of the feed rolls.

52. Apparatus as in claim 51, and curved blade means on said movable means movably bodily therewith into the line of feed of such panels to divert the panels.

53. Apparatus of the class described, comprising a support, a driven feed roll journalled relative to the support, means for imparting successive alternate oppositely directed accordion folds to a sheet and delivering same to said support, curved blade means, a supplemental feed roll journalled adjacent to said blade means, means for moving said blade means and roll transversely of the general plane of the accordion folded sheet on said support whereby said roll compresses the folded sheet against said feed roll and in conjunction with said curved blade means to jointly feed said accordion folded sheet against the blade means to direct same angularly therefrom.

54. Apparatus of the class described, comprising a support having a generally planar surface, a feed roll journalled on the support with its upper surface generally tangential to the plane of said support, means for folding a sheet into plural alternately oppositely directed accordion folds defining panels and delivering successive panels of said sheet on said support, curved blade means, a roll, means for moving said blade transversely of the panels on said support, means for synchronously moving said roll against the panel overlying said feed roll whereby the panels are fed toward and react curvilinearly from said curved blade to move out of the plane of said support.

55. Apparatus of the class described, comprising a generally planar surface, a pair of feed rolls driven in opposite directions and having their surfaces generally tangential to the generally planar surface, means for forming a sheet into plural oppositely directed panels successively disposed on the planar surface, blade means, means for moving said blade means transversely of such panel toward said feed rolls, and roller means movable against the panels to form with one of said feed rolls feeding means projecting said panels against said blade to divert the panels from the generally planar assembly and between said pair of feed rolls.

56. Apparatus as in claim 55 and supplemental means movable against the panel to form with the other of said feed rolls feeding means projecting said panels against said blade to divert the panel from the generally planar assembly through and between said feed rolls.

57. Apparatus of the class described comprising a generally horizontal effective tray, movable feeding means on the tray comprising first and second oppositely rotating generally parallel rollers having a mutual feeding line generally normal to said tray, means converting a generally planar flexible sheet into an accordion folded rudimentary packet on said tray overlying and substantially contacting said feeding means, said rudimentary packet comprised of panels in general parallelism with each other and with said tray, said rudimentary

packet being longer in the line of folds between panels than in width transversely thereof, said first roller of said feeding means having a line of feed substantially parallel to the line of folds between panels, and complementary feeding means, means mounting the complementary feeding means for movement between a position spaced from the rudimentary packet and a position contacting and compressing same against said first roller of said feeding means, said complementary feeding means comprising a roller parallel to said first roller.

58. Apparatus of the class described comprising a generally horizontal tray, means converting a substantially planar flexible discrete sheet into a rudimentary packet on said tray, said rudimentary packet comprised of plural panels having integral accordion-type folds and having a length longer in the line of folds than the width transverse of said folds, an element of cross folding means normally out of operative juxtaposition to said sheet during the conversion thereof into the rudimentary packet on said tray, means effecting relative motion between said rudimentary packet and said element in the line of folds into operative juxtaposition of said element and said rudimentary packet, sensing means operative relative to the sheet from which said rudimentary packet is formed distinguishing between sheets of smaller than a predetermined width comprising a minor width and sheets of larger width than said predetermined width comprising a major width, said sensing means controlling said means effecting said operative juxtaposition to locate same at a predetermined minor distance from one edge of such rudimentary packet in the case of a sheet of minor width and to locate same at a predetermined major distance from said one edge greater than said minor distance in the case of a sheet of major width said element comprising creasing means substantially normal to the line of folds of said rudimentary packet, and means effecting relative motion of the rudimentary packet and said element toward each other in either of their relatively operative juxtapositions cross folding the rudimentary packet about said element.

59. Apparatus of the class described comprising first means accordion folding discrete sheets into rudimentary packets, second means cross folding rudimentary packets into packets of predetermined lateral dimensions, said discrete sheets potentially comprising in relatively random presentation to the apparatus sheets of relatively minor widths not greater than a maximum minor width and of relatively major widths greater than said maximum minor width, and means automatically responsive to the width of an instant discrete sheet controlling said second means and selectively imparting a single cross fold to a rudimentary packet formed from a sheet of minor width and two successive cross folds to a rudimentary packet formed from a sheet of major width.

60. Apparatus for folding and cross folding two substantially successive flexible discrete sheets of which one is of a minor width not exceeding a maximum minor width and the other of which is of major width greater than said maximum minor width, comprising means imparting successive accordion type folds to both sheets forming first and second respective rudimentary packets, means automatically responsive to the width of an instant sheet imparting a single cross fold to the rudimentary packet formed of the sheet of minor width and forming a packet of given lateral dimensions, and imparting two successive cross folds to a rudimentary packet formed of the sheet of major width, forming a packet of the same said given lateral dimensions.
